UNITED STATES PATENT OFFICE

2,052,343

PLASTIC FORMING APPARATUS

David Irvin Du Bois, Millville, N. J., assignor to
Whitall Tatum Company, Millville, N. J., a
corporation of New Jersey

Application June 21, 1930, Serial No. 462,802

52 Claims. (Cl. 49—36)

The present invention relates broadly to the art of handling and molding plastics, and more particularly to apparatus for the feeding and molding of glass, although the utility of the invention is not limited with respect to the particular substance being handled.

With the developments in the art of glass working machinery, and particularly with apparatus working at relatively high speeds, whether continuously or intermittently, considerable difficulty has been experienced in the proper delivery to such apparatus of gathers or charges of glass. Where a feeding mechanism has been used in conjunction with a forming mechanism, it has always been considered necessary to control the forming mechanism by the feeding mechanism and to accommodate the speed of movement of the forming mechanism by the feeding characteristics or other limitations of operation of the feeding mechanism.

In constructions having the purpose of effecting the delivery of a predetermined charge of glass at the required time to a forming machine, and in which it was intended that the forming operation should be synchronized to the operation of the feeding mechanism, it has heretofore not been possible to obtain the flexibility of operation desired.

In actual operating conditions, it is necessary to provide a forming machine capable of forming articles of a wide variety of shapes, sizes and weights. With each change in the characteristics of the article being formed, particularly where there is any material variation in the weight of such article, it is desirable if not imperative, to change the speed of operation of the forming machine. With a combined feeding and forming machine, it is obviously necessary to make changes in the speed of operation of the feeding mechanism in accordance with such changes in the speed of operation of the forming mechanism. It not infrequently happens, moreover, that due to some mechanical difficulty with a part or parts of the forming machine, it is necessary to temporarily cut that machine out of operation. If the forming machine and the feeder were directly interconnected, it would be necessary, with some of the installations of the character referred to, to also stop the operation of the feeder during the time the machine is cut out. This is objectionable in that such a cessation of the operation of the feeder may result in "freezing" up of the same.

In accordance with the present invention, I provide a combined feeding and forming machine in

which the feeding machine and the forming machine are driven by common actuating mechanism, and in which the feeder may be continued in operation regardless of whether the forming machine is operated or idle. In this manner, once 5 the desired feeding temperature or condition is obtained in the glass being handled, the feeding mechanism may be maintained in normal operation to keep this condition during the periods of temporary shut-down of the forming machine. 10

In practical operation of machines of the character herein contemplated, changes in the temperature of the glass are not infrequently encountered. The hotter the glass, the more quickly it is delivered to the forming machine, 15 while as the glass tends to cool off, longer and longer periods of time are required in order to effect the proper delivery of a charge. While an endeavor is made to maintain the glass at a proper temperature, it is sometimes necessary to 20 effect an adjustment capable of temporarily caring for such a change in temperature conditions. In accordance with the present invention, there is provided a mechanism operative at will during the operation of the complete machine, for tem- 25 porarily accelerating or decelerating the speed of operation of the feeding mechanism, and for advancing or retarding its cycle relative to the cycle of the forming machine. Such an acceleration or deceleration is obviously necessary in order 30 to effect the change in the timed relation between these two cycles, and in order to advance or retard one cycle relatively to the other.

A proper timing of the cycles is a matter of painstaking adjustment, and were the timing to 35 be thrown out of step in case the forming machine were temporarily thrown out of operation, the work of adjusting previously done would be lost. It is obviously not only desirable, but under certain conditions necessary, that, when operation of the idle mechanism is resumed, the start be timed so that the cycles of the feeding mechanism and of the forming mechanism continue in step as previously adjusted. In accordance 40 with the present invention, there is provided 45 mechanism effective for obtaining the desired interconnecting of the two mechanisms, and operative for only interconnecting these mechanisms when the respective cycles bear the desired relationship one to the other.

It is well recognized by those skilled in the art that a considerable problem is presented in the bringing up to speed of a machine involving the mass of a machine of the character herein contemplated. If change speed mechanism un- 55

der the control of the operator is provided, such as to permit a stepping up in the speed of the parts, the results obtained are dependent entirely upon the skill of the particular operator in charge of the machine. In accordance with this invention, difficulties of this character are obviated; and there is provided a driving mechanism automatically controlled and effective for insuring commencement of operation at some predetermined relatively low speed with a transition, under predetermined conditions only, from this speed to a higher speed.

The invention also contemplates the provision of controlling mechanism such that upon stopping the operation of the machine, it is thereafter only possible to resume operation by first going through the low speed condition and thereafter changing automatically to the high speed condition. Claims to the features set forth in this paragraph and in the preceding paragraph are contained in my copending application, Serial No. 586,785, filed January 15, 1932.

In the actual operation of a combined feeding and forming unit, it is sometimes desirable to change the time of occurrence of certain of the operations, such for example, as the taking-out operation, with respect to the charging or feeding operation. Where such a change is made, while maintaining a fixed point of charging, it is obviously necessary to provide means whereby such a change does not destroy the predetermined timing or sequence of related operations. In accordance with my invention, I provide a control unit, adjustable as a whole to predetermined positions, circumferentially of the forming machine, and effective for making changes as desired without interfering with the normal sequence and timing of related operations.

Where this change is effected with respect to the taking-out operation, all of the controlling means incidental to the control of functions which must be timed relatively to the taking-out, are mounted on such a control unit so that they are also bodily advanced or retarded as the taking-out station is changed. Such operations, for example, may include the opening of the mold, the movement of some part thereon to eject or otherwise move the formed article from the mold, the operation of the take-out mechanism, the release of such article from the take-out mechanism and its proper delivery onto a conveyor or support, and the return of the ejecting or delivery means and take-out mechanism. My invention provides a control unit possessing these and other desirable features of operation.

While maintaining a predetermined timed relation between the delivery of the glass into the mold and the performance of subsequent operations thereon, it is frequently desirable to change the duration of some of such operations in accordance with the characteristics of the glass or the article being formed. In accordance with the present invention, provision is made for effecting at will during the operation of the machine, such a change in the duration of certain of the subsequent operations while maintaining the desired timed relationship between such operations and the operation of the machine. Provision is also made for effecting a change in the time of commencement of such operations so as to adapt the machine to the production of a wide variety of different articles and different speed conditions.

The present invention further contemplates a novel distribution of pressure fluid from a common source, under different pressure conditions,

to the different units which it is desired to operate by means of such pressure.

In the accompanying drawings in which for purposes of illustration only and not by way of limitation, I have shown a preferred embodiment of the present invention, it being understood that changes in the construction, character and relation of the parts, as well as in the manner of the operation thereof, may be made without departing from the spirit of the present invention or the scope of the broader claims.

Figure 41 is a view partly in elevation and partly in vertical section of the bottom plug safety switch;

65 Figure 42 is a plan view of the mechanism shown in Figure 41;

Figure 43 is a view in side elevation of the mechanism for shifting the main clutch of the machine, and is taken on line XLIII—XLIII of Figure 30;

70 Figure 44 is a detail sectional view on line XLIV—XLIV of Figure 43;

75 Figure 45 is a view in elevation from line XLV—XLV of Figure 30, illustrating the auto-

matic control mechanism for the change speed gearing;

Figure 46 is a view in elevation of the solenoid and related mechanism for shifting the main clutch of the machine, and is taken at 5 XLVI—XLVI of Figure 30;

Figure 47 is a wiring diagram of the controlling circuits for the main driving motor;

Figure 48 is a plan view of the conduits for the circuits shown in Figure 47, and also showing the 10 signal lights and the automatic switch controlling the same.

Figure 49 is a side elevational view of a portion of the distributing valve;

Figure 50 is a cross sectional view on the line 15 L—L of Figure 49;

Figure 51 is a detail sectional view of a press head valve;

Figure 52 is a detail sectional view of a mold cylinder valve; 20

Figure 53 is a detail sectional view of a cooling control valve; and

Figure 54 is a detail sectional view of a check valve.

For a general understanding of the present invention, reference may first be had to Figures 1, 5 and 6 of the drawings, Figure 6 showing diagrammatically the sequence of operations of the machine, starting with the position in which a mold receives a mold charge, and proceeding with 25 such mold through the different arcs of travel during which pressing, removal of the screw peg, and opening of the mold take place, and concluding after transfer of the molded article to a conveyor and mold closing have occurred. As will be 30 noted from these figures, the machine comprises twelve molds, though a greater or less number could obviously be employed. Since each mold is similar to the others, and a similar cycle of operations is performed in connection with each, the 35 description of one mold and its cooperating forming mechanism will make clear the operation and characteristics of the other eleven.

The mold table, which carries the molds, after 40 coming up to speed, rotates continuously at such speed, the several operations performed on the

glass taking place as the molds travel with the table. At the position marked "charging" in

Figure 6, a charge of plastic glass is delivered

to the mold which is being considered as typical

50 of the others in this description. The mold

which, it will be noted, comprises relatively movable sections, has previously been closed, and is

therefore ready to receive the charge. During

travel of the mold, a press head, with a screw

55 peg previously cooled and lubricated, lowers by

reason of air pressure within a press head cylinder

(shown in section in Figure 15) and effects press-

ing of the glass to the desired shape. Before the

press mechanism is permitted to completely rise,

60 the screw peg, provided with threads to form cor-

responding threads in the glass article, is screwed

out of the article. The press mechanism is then

completely elevated. As the mold approaches the

take-out position, it is opened, leaving the article

65 supported on the bottom plug of the mold. The

latter is thereupon extended radially; and the

take-out mechanism transfers the hot article onto

a conveyor. The mold is then closed ready for

another cycle of operations.

As shown in Figures 1 and 5, the machine gen-

erally comprises a base 50 mounted on wheels 51

so that the machine, which is quite heavy, may

be moved to desired locations in the shop. A

table support 52 is carried by the base 50, this

support providing an upwardly extending collar 53 surrounded by the mold table 54. The mold table includes a hub 55 journaled on the collar 53, a ball thrust bearing 56 between the table 54 and the support 52 taking up the weight of the table. On the table is supported a plurality of molds 57, with each of which a forming mechanism, later to be described, cooperates.

10 *Feeding*

A gob chute 58, which is shown in Figures 2 and 4, is arranged beneath a glass feeding mechanism, and is designed to transfer gobs successively from the feeder to the orbitally moving molds. The orifice through which the plastic glass flows or is extruded is shown at 59. Beneath the orifice is disposed shearing mechanism 60, which may be of any suitable type; and since shearing devices of different types are well known, 15 it is not necessary to describe such mechanism in detail. It should be noted, however, that my invention provides improved driving connections for the feeding mechanism to insure that gobs shall be formed and the mold table rotated in 20 synchronization.

The body portion 61 of the gob chute is secured on a frame 62. The gobs are received through a tunnel-shaped mouth 64, which is normally disposed beneath the shearing mechanism 60. The 25 body portion 61, and likewise the entrance portion 64 are sufficiently inclined to insure sliding of the gobs within the same by gravity. The frame 62 is mounted on a vertical pivot pin 65 carried by the base 50, through the gear housing K of the 30 driving mechanism hereinafter described, a ball thrust bearing 66 being provided to take up the weight of the chute and frame. A lever arm 67 projects from the frame 62, and a pull rod 68 (see Figure 2) actuated by a lever arm 69 is pivotally connected to the lever arm 67 at 70. The lever arm 69 is secured to a shaft 71 which is turned by mechanism later to be described (see Figures 30 and 45). As shown in Figure 2, a pair of ears 72 is formed on a pedestal portion of the 35 gear housing. These ears 72 are formed with depressions 73 which cooperate with spring pressed latches or pawls 74 carried by the frame 62. The latches 74 normally retain the frame 62 in the position shown in Figures 2 and 4, being 40 adapted to drop into the depressions 73 when the frame 62 is returned to its normal position.

A waste glass chute 80 is arranged with its receiving end beneath the receiving portion 64 of the gob chute 58. The chute 80 is stationary, and 45 is arranged to deliver gobs to a point from which they may be returned to the glass furnace. It is apparent, therefore, that if the gob chute 58 be swung to inoperative position, the gobs will not be delivered to a mold, but will fall into and will be 50 carried away by the chute 80. If desired, the delivery portion 75 of the gob chute 58 may be pivoted for independent swinging movement; and the chute, as illustrated, is so constructed. As shown 55 in Figures 2 and 4, a support 76 is hinged at 71 to the frame 62, a spring 78 extending between the frame and the support 72 so as to bias the frame toward the position shown in Figure 4. An abutment 79 is carried by the support 76 in such a 60 way as to engage the frame 62 when in the position shown in Figure 4. The delivery portion 75 is downwardly curved so as to change the direction of movement of the gobs as they slide down the chute and cause them to fall substantially 65 vertically into the molds. Due to this change in

the direction of movement of the mold charges, the bottom wall of the delivery portion may be omitted, and only the other three sides retained. It is apparent, therefore, that the narrowed-in delivery portion of the gob chute is accessible, so 5 that if the glass tends to stick therein, the same may easily be removed.

The driving connections for the shearing mechanism 60 are partially shown in Figure 3. Part of the framework of the feeding mechanism 10 is shown at 81, a bearing 82 being carried thereby. The lower end of a shaft 83 which drives the feeding mechanism including shearing mechanism 60 is shown mounted in the bearing 82 in the framework 81. Connected thereto by a flexible coupling 84 is a hollow shaft 85. Slidably received within the hollow shaft, and feathered thereto, is a shaft 86. It is obvious, therefore, that shafts 85 and 86 together compose a shaft whose length is adjustable, and which, nevertheless, may drive through the flexible coupling 84, the shaft 83, and accordingly the shearing mechanism 60. A pedestal 87 is located at a suitable point on the floor of the shop to support the mechanism above described. An elevating screw 25 89 is mounted in the pedestal 87, and has secured thereto a bearing head 90 formed with an annular flange 91. This flange engages and supports a casing 92 which is provided with a bearing 93 for the lower end of the shaft 86. A horizontal extensible shaft 94 similar to the vertical shaft which, as above described, is composed of the shafts 85 and 86, projects within the casing 92, the latter providing a bearing therefor at 95. Beveled gearing 96 connects the vertical and 30 horizontal shafts in driving relation. As shown in Figures 1, 3 and 30, the base 50 carries a differential housing 98 formed with an upwardly projecting bearing 99 in which is journaled a vertical shaft 100. A gear casing 101 is rotatably 35 mounted on the upper end of the vertical bearing 99. It will be noted that a flange 102 on the bearing 99 engages a groove in the casing 101, being slidably held therein by a ring 103. An end of the horizontal shaft 94 projects within the 40 casing 101, and beveled gearing 105 connects shafts 100 and 94 in driving relation. The driving connections just described connect the feeding mechanism including shearing mechanism 60 with a prime mover supported on the base 50, 50 these connections nevertheless permitting movement of the base relative to the feeding mechanism.

The casing 92 is of a construction similar to that described for the casing 101. It will thus be 55 apparent that the two swivelled casings in combination with the extensible shaft 94 enable the base 50 to be variably positioned relative to the pedestal 87.

The above description is limited to those portions of the feeding mechanism by means of which the feeder and shears per se are operated for effecting a severance of the glass supply into gobs of the desired characteristics. The operative connections for effecting the driving of the above mechanism in the desired timed relation to the operation of the forming machine will hereinafter be described in detail.

The mechanism just described having been 70 operated, will effect the desired gob formation and delivery thereof, by means of the chute 58 into one of the molds preparatory to a forming operation which is herein preferably accomplished by pressing.

Pressing

In Figure 16 the press mechanism is illustrated in its completely elevated position ready for the commencement of a forming operation. This operation is accomplished by means of a fluid pressure motor which will hereinafter be described in detail, which is effective for producing a lowering movement of the press head, screw peg and associated parts. During this lowering movement of these parts they will pass through a position illustrated in Figure 16a, and continued descent will move the parts into the pressing position illustrated in Figure 16b. The relative time of commencement of the forming operation, as well as its duration, are both illustrated in this figure.

The duration must be determined by two characteristics which, to a large extent, oppose each other. One of these is the necessity of as short a period of pressing as possible in order to speed up the production of the machine, and the other is a pressing period of sufficient duration to insure sufficient setting of the glass, and particularly the threaded portion thereof, to cause the same to be self-sustaining upon withdrawal of the screw peg.

In Figure 16b, there is shown a mold 57 with a charge of glass therein as delivered by the feeding mechanism. The desired shaping of this charge is herein illustrated as being accomplished by a screw peg 110 secured to the lower end of the screw peg stem 111 as hereinafter described more particularly in connection with Figure 19 of the drawings. Surrounding the screw peg stem is a sleeve 112 formed intermediate its ends with diametrically opposed slots, as illustrated more particularly in Figure 16c of the drawings, and adapted to receive portions of diametrically opposed worm wheels 113 carried by shafts 114 journaled in a suitable housing 115. These shafts are adapted to be frictionally held against easy rotation by means of springs 116, the degree of compression of which is adjustably controlled by means of nuts 117. The compression springs at their outer ends bear against the under sides of these nuts and at their inner ends directly against friction disks 118 cooperating with one side of the housing 115. The shafts 114 at their other ends are provided with disk shaped friction heads 119 bearing against the opposite side of the housing.

By reason of this construction it will be apparent that as the springs are compressed, rotation of the shafts 114 will be retarded by reason of the frictional resistance between the disks 118 and 119 and the housing 115. In order to permit adjustment of the character referred to, the key connection between the worm wheels 113 and their shafts 114 is such as to permit relative axial sliding movement, whereby the heads 119 may be drawn tighter and tighter against the side of the housing as the springs are compressed.

The screw peg stem 111 adjacent the slotted portion of the sleeve 112 is threaded, as clearly indicated in Figure 19 for cooperation with corresponding teeth formed on the worm wheels 113.

Secured to the lower end of the sleeve 112 is a petticoat 120 having a shape such as to impart a desired skirt formation to the insulator being produced. Due to the cooperation between the slotted portions of the sleeve 112, which bear against the sides of the worm wheels 113, rotation of the sleeve and its associated parts during vertical movements of the press mechanism is prevented. Such vertical movement is accomplished

by securing to the upper end of the screw peg stem 111 a gear 121 bearing at its lower side against a suitable shoulder on the stem, and held in position thereon by a clamp nut as clearly illustrated in Figure 19.

Axially aligned with the screw peg stem is a piston rod 122 having a threaded portion at its lower end adapted to adjustably receive a cross head 123 herein illustrated as comprising a pair of jamb nuts carried by the piston rod and adapted to be adjusted axially thereon to the desired position.

The lower end of the piston rod is hollowed, as illustrated in Figures 16a and 19, to receive a guide bushing forming an end guide for the upper end of the screw peg stem, which is telescopically mounted with respect thereto.

Also adjustably carried by the piston rod 122 is a spring plate 124 held in adjusted position by means of clamp nuts as clearly illustrated in the figures under consideration. Slidably mounted within suitable openings in the spring plate are spring guide rods 125 secured at their lower ends to the housing 115 and lying on diametrically opposite sides of the screw peg stem and piston rod. Carried by the rods 125 are compression springs 126 bearing at their lower ends against the housing 115, and at their upper ends against the under side of the spring plate 124. Secured to the lower side of the housing 115 is a follower or mold sealing ring 127 surrounding the petticoat 120 and slidably relatively thereto. This mold sealing ring and the mold 57 are so shaped as to permit the two to closely interfit, as illustrated more particularly in Figure 16b of the drawings, whereby to limit the upward movement of the glass charge during the forming operation.

The initial lowering movement of the piston rod 122 causes the press mechanism to move downwardly as a unit until such time as the mold sealing ring 127 comes into contact with the upper surface of the mold 57, by means of which continued descent of the mold sealing ring and housing 115 is prevented. Continued descent of the piston rod 122, however, is effective for compressing the springs 126 whereby a gradually increasing pressure is exerted on the mold sealing ring. During the building up of this pressure, the piston rod 122 telescopes over the screw peg stem 111 until such time as the lower surface of the cross head 123 comes into engagement with the upper surface of the gear 121. Thereupon, continued lowering movement of the piston rod 122 will be effective for bodily lowering the screw peg stem 111 and its associated parts, including the sleeve 112 and the petticoat 120, this operation being effective for sliding the screw peg 110 and petticoat 120 through the mold sealing ring and into shaping engagement with the glass charge within the mold.

Lowering movement of the screw peg stem 111 and sleeve 112, as just described, is permitted by reason of the rotation of the worm wheels 113 against the frictional resistance before described.

As is apparent from Figure 19 of the drawings, the screw peg 110 is bodily removable, in case replacement is desired, or in case of a change in the characteristics of the article being formed, from the screw peg stem 111. This removal is permitted by providing the lower end of the screw peg stem 70 with a coupling 128 threaded into the lower end of the screw peg stem, the upper end of the screw peg being internally threaded to cooperate therewith.

For reasons which will be hereinafter more

fully apparent, the coupling 128 is provided with a left hand thread, so that upon rotation of the screw peg stem and screw peg as required for removing the same from a formed article, the 5 screw peg will not be loosened relatively to its mounting. By providing a coupling of the character described, bodily replacement is made possible in case the threads between the same and the screw peg become unduly worn.

10 Also, as shown in Figure 19 of the drawings, the sleeve 112 at its upper end is recessed to receive therein ball thrust bearings 129, one of which is preferably provided both above and below a collar 130 formed on the screw peg stem, 15 and effective for taking the thrust on the stem during the rotation thereof as hereinafter set forth.

For effecting the desired vertical movements of the press mechanism just described, there is 20 provided a piston 132 secured to the upper end of the rod 122. A rod 133, arranged co-axially with the piston rod 122, is secured to the upper side of the piston 132, and projects through the upper end of a cylinder 134 within which the piston 132 is operable. The upper end of the rod 133 is rounded, so that a roller 135 carried by a shaft 136, may move over the same to limit upward or return movement of the press mechanism. The shaft 136 is mounted in a slide frame 25 137, this slide frame being spring pressed (Figure 5) into position to place the roller over the end of the rod 133 for the purpose above described. As shown in Figure 5, the inner end of this slide frame 137 is pivotally connected to a lever 138 having a fulcrum at 139 and provided at its lower end with a cam roller 140.

At times, in order to permit certain repair operations on the press mechanism, it is desirable to effect a raising of the press mechanism. 40 In order to permit such a raising of this mechanism, it is obviously necessary to provide some means for retracting the slide 137 with its roller 135 from holding engagement with the upper end of the rod 133. This may be accomplished, at 45 the pleasure of the operator, by a camming-out lever 131 of suitable construction adapted to be swung from its full line position of Figure 5 into the dotted position illustrated for causing the camming projection on the end thereof to retract the slide 137 and its associated parts. This 50 camming-out lever may be of any suitable construction, and may be provided with a suitable holding pawl 131' (Fig. 15), for maintaining it in its dotted line position.

55 The pressure fluid for reciprocating the piston 132 within the cylinder 134 is supplied by a pipe 171 (Figure 22) from a central distributing member 166, hereinafter referred to and illustrated in greater detail. The distributing member is 60 carried by the machine in such manner as to be effective about the axis of rotation thereof. To the upper end of the cylinder 134 is connected a pipe 178, while to the lower end of the cylinder is connected a second pipe 179, both of these 65 pipes, as well as the supply pipe 171, being connected to a press head valve cylinder 180 containing a press head valve provided with a stem 175 carrying a cam roller 176, as illustrated in Figure 5 of the drawings.

70 In Figure 51 of the drawings one of the press head valves is illustrated in detail.

The cam roller is adapted to be actuated for shifting the press head valve in one direction or the other by suitable cam plates carried by the 75 upper portion of the machine, as illustrated more

particularly in Figure 8 of the drawings, and hereinafter described. The operation of the press head valve is such as to initially supply fluid under pressure to the upper end of the cylinder 134 for lowering the press mechanism in the 5 manner previously set forth.

It is desired that the connections for supplying fluid under pressure shall be such as to permit a free flow of fluid to the cylinder, with a throttled or controlled exhaust therefrom by means of 10 which the rapidity of movement of the piston 132 may be controlled at will. This movement is accomplished by providing both ends of the cylinder 134 with a check valve assembly 181, as illustrated in detail in Figure 18, the cylinder and 15 check valve assemblies being illustrated in co-operative relationship in Figure 17. These two assemblies are of identical construction each effective for giving a fluid flow to and from the cylinder 134 of the character described. 20

Each check valve assembly includes a chamber 182, the chamber 182 of the upper assembly being in communication with the connection 178, while the corresponding chamber of the lower assembly is in communication with the connection 179, which connections are controlled by the press head valve. 25

Each of the assemblies also includes a passage 183 suitably formed therein and functionally between the chamber 182 and the cylinder and 30 constituting a part of the flow path between the two, each passage including two extensions 183', as indicated in dotted lines in Figure 18 leading into the end of the cylinder with which the assembly cooperates. One side of the passage 183 35 is closed by a cover plate 184 having formed integrally therewith a projecting boss 185 having a bore 186. A recessed plug 187 is threaded into the outer end of the boss and forms a closure therefor. Reciprocable within the bore 186 is 40 the stem of a check valve 188 which cooperates with a port 189 extending between the chamber 182 and the passage 183. For normally urging the valve 188 into the position illustrated in Figure 18, there is provided a spring 190 carried 45 partly by the hollow valve stem and abutting at its outer end against the recessed plug 187.

Also extending between the chamber 182 and the passage 183 in each of the valve assemblies is an exhaust port 191 adapted to be controlled by 50 a valve 192 whose stem 193 is threaded in the cover plate 184 and projects therebeyond a sufficient distance to permit desired manual adjustment of the valve, the valve being held in an adjusted position by a suitable wing nut as illustrated. 55

Assuming that the press head valve within the casing 180 has been so actuated as to supply fluid under pressure through the connection 178 to the chamber 182, the pressure within the chamber 60 182 is sufficient to unseat the valve 188 whereby a free flow of live air occurs from the chamber 182 through the port 189 and passages 183 and 183' to the upper end of the cylinder 134, thereby lowering the piston 132 therein. While the setting of the exhaust valve 192 will be such as to permit a small portion of the air from the chamber 182 to flow past the same, any such air will join the main supply in the passage 183 and be delivered to the cylinder 134. 70

During such supply of air under pressure to the upper end of the cylinder 134 through one of the valve assemblies, the air below the piston 132 will be exhausting therefrom through the other assembly. The return or exhaust of this air will 75

be controlled by the setting of an exhaust valve 192 in such assembly, it being obvious that the spring 190 of such assembly will maintain its valve 188 in position to close the port 189 therein 5 and prevent reverse flow of air from the cylinder through the port 189. This necessitates all of the air being exhausted from the cylinder, passing the valve 192, and thereby makes it possible to control at will the speed at which the piston 10 travels by a suitable regulation of the position of the exhaust valve.

Doping and cooling

At such an interval of time prior to each pressing 15 operation that any coating supplied to the screw peg 110 will not be completely vaporized by the temperature thereof and still will not remain thereon in such quantities as to vaporize and produce gas pockets within the glass after the screw 20 peg has been lowered thereinto, the screw peg is subjected to a spray of suitable material having the combined effect of coating or "doping" the same and effecting a partial cooling thereof. This operation may be accomplished by providing 25 around each of the cylinders 134 a dope chamber D adapted to be periodically filled through a suitable stand pipe 199, a gauge glass G being provided for indicating the amount of dope within each of the reservoirs D. Below the gauge glass, 30 the continuation 199' of the filling pipe 199 is provided with a control valve 194, conveniently in the form of a needle valve with a suitable hand wheel control, whereby the needle valve may be accurately adjusted, in a manner similar to an ordinary drop feed lubricator, to determine the rate at which lubricant passes from the reservoir 35 into the connections below the valve.

The application of any accumulation of dope 40 below the needle valve to the screw peg is conveniently effected by utilizing the air which is exhausted from the next preceding cylinder 134. This may be accomplished by providing the press 45 head valve cylinder 180 with a connection 195 (Figure 22) extending around the cylinder, as indicated in Figure 23, and then joining the pipe 199' at a point below the needle valve 194.

By reason of this construction, when a preceding 50 cylinder 134 is exhausting air from the lower end thereof due to the descent of the piston therein, this air passes therefrom through one of the valve assemblies into and through the press head valve and by way of a connection 195 into the extension 199'. From the point of connection 55 there leads a common pipe 200 in which the dope which has dropped past the needle valve has accumulated. This accumulated dope is forced from the pipe 200 by the exhaust air just referred to and the mixture of exhaust air and dope is sprayed onto the peg 110 by the nozzles 201.

Extending outwardly from the distributing member 166, as illustrated in Figure 5, and constituting a supporting, carrying and positioning means for the various press head cylinders, is an upper frame F. This frame is provided adjacent 65 its outer portion with an annular chamber 202. Each press mechanism is provided with an independent connection 203, as illustrated in Figure 22, with the annular chamber 202. Fluid under 70 pressure being maintained in the annular chamber in the manner hereinafter described, the flow of such fluid from the chamber through the individual connections 203 is controlled by individual cooling fluid valves 204 which are secured to the periphery of the frame F at equi-distantly 75 spaced points, as illustrated more particularly in

Figure 1, there being one valve in substantial radial alignment with each press mechanism. Each of these valves is provided with a stem 205 (Figure 5) projecting downwardly therefrom in alignment with an adjustable stop 206 carried by 5 a bracket 207 secured to and projecting outwardly from a spring plate 124.

In Figure 53 one of these cooling control valves is illustrated in detail.

Each of the individual cooling control valves is 10 normally open to permit the unobstructed flow of cooling fluid from the annular chamber 202 through the same and downwardly through flexible connections 203' secured to pipe sections 208 (Figure 16a) threaded into the piston rod 122. 15 Each of the piston rods is hollow, as illustrated more particularly in the figure just referred to, and the short pipe sections 208 communicate with this hollow bore.

As before described, the upper end of each of 20 the screw peg stems 111 is telescopically mounted in the lower end of its cooperating piston rod and is in turn provided with a hollow bore 210 extending therethrough and in communication with the axial opening in its cooperating piston rod 25 whereby cooling fluid supplied from the annular chamber 202 may pass, by way of connections set forth, directly into the interior of the screw peg stem. The coupling 128 utilized for securing the screw peg in position on the stem is also hollow 30 and carries a tubular extension 211 terminating adjacent the lower end of its hollow screw peg and effective for discharging any received air into the screw peg adjacent the lower end thereof. 35 This air is permitted to escape upwardly around the tubular extension 211 and escapes from the screw peg through ports 212 formed in the upper end thereof.

From the foregoing description it will be apparent that with the press head mechanism in 40 lower position cooling air is continuously delivered to the screw peg carried thereby for cooling the interior thereof, this cooling operation continuing until the press head mechanism is raised to such a position as to bring the stop 206 into 45 engagement with the valve stem 205 and move the cooling fluid control valve to closed position.

If desired, there may be provided a by-pass connection 213 between the lines 203 and 203', as 50 illustrated in Figures 21 and 23, each of these by-pass lines being provided with a control cock 214 adjustable at the will of the operator, whereby a greater or less amount of cooling air may by-pass the valves 204 for continuously supplying a predetermined amount of cooling air to the interior 55 of the screw pegs. Such a construction has been found desirable when operating the machine in extremely warm weather where continuous cooling even with the press head mechanisms in elevated position is found desirable.

60

Screw-out

It will be noted from Figure 5 that a horizontally extending shaft 150 is journaled at its inner end in a bearing 151 insertable in the table support 65 52. Its outer end is journaled in a bearing 153 provided in the gear housing K. A gear 155 secured to the outer end of the shaft 150 is driven from the main driving mechanism of the forming machine in a manner later to be described.

Projecting upwardly from the base 50 is a central column 156 surrounded by sleeve bearings 157 provided for a cylindrical driving member 158 concentrically disposed around the central column. Beveled gearing 159 connects the shaft 150 70 75

and this cylindrical driving member. Carried by the upper frame F is a horizontally extending shaft 160 so mounted as to project substantially radially from the cylindrical driving member with its 5 inner end adjacent thereto.

Bevel gearing 161 connects the cylindrical drive member 158 and the shaft 160, while similar gearing 162 connects the outer end of the shaft 160 with a vertically extending shaft 163 carried by 10 and extending through the upper frame F. Carried by the upper end of the shaft 163 is a pinion 164 meshing with a spur gear 165, the hub of which surrounds and is carried by the distributing member 166, the outer part of the distributing member herein being illustrated as formed integrally with the upper frame F.

The spur gear 165 in turn meshes with a series of equi-distantly spaced screw out driving gears 167, one of which is provided for each of the press 20 head mechanisms. Each of the screw out driving gears is carried by the upper end of a substantially vertically extending shaft 168 positioned within standards S. These standards serve as tying and bracing means between the upper frame F 25 and an intermediate frame f herein illustrated as being of annular shape. The intermediate frame is supported in concentric relation to the central column 156 by sub-standards s, one of which is preferably provided intermediate each 30 pair of molds. In accordance with the preferred embodiment of the invention, each of the sub-standards has a height slightly greater than the vertical dimensions of the molds, whereby the molds may work freely below the intermediate frame and may be readily removed or replaced 35 from the table 54 without disturbing such intermediate frame.

It will be understood from the preceding description, that there is one of the standards S with 40 its contained shaft 168 and associated parts for each press head. Inasmuch, however, as these parts are all of identical construction, only one of them will be described in detail, and for this purpose reference may be had to Figure 5 of the 45 drawings.

Feathered to the upper end of each shaft 168 above its gear 167 is a toothed clutch member 169, the teeth on which are adapted to cooperate with correspondingly shaped teeth on the gear 167. A 50 clutch shipper 170 engages a groove in the feathered clutch member 169 to shift the same longitudinally of the shaft 168 upon actuation thereof.

The gearing, which in Figure 5 is shown beginning at the pinion 155 and ending with the 55 gear 167 constitutes a continuous gear train, which is continuously driven whenever the main driving mechanism of the forming machine is in operation. The screw-out clutch mechanism just described is provided for the purpose of interconnecting or disconnecting the screw out mechanism with or from this gear train at predetermined times in the operation of the machine, such an interengaging or disengaging of the parts being effected each time the shipper 170 is actuated.

For driving the gear 121 of the press head mechanism from the shaft 168, there is provided a gear 172 slidably splined to the shaft 168. This gear is adapted to be moved longitudinally of the shaft 70 by a support 173 carried by or constituting part of the gear casing 115 of the press mechanism and projecting inwardly therefrom into the standard S. If desired, it will be understood that the gear casing and the standard may be so shaped 75 as to afford a sliding engagement therebetween

during the reciprocation of the press mechanism for the purpose of maintaining the desired alignment between the press mechanism and its mold. Intermediate the gear 172 and the gear 121 is an idler 174, by means of which the desired rotation 5 may be transmitted from the shaft 168 to the screw peg stem for effecting an unscrewing operation.

As before described, the screw peg stem is provided with an intermediate threaded portion 10 meshing with the teeth on the worm wheels 113. The pitch of the threads on the screw peg stem preferably bears such relation to the pitch of the threads on the screw peg 110 that upon rotation of the screw peg stem the threaded portion thereof will effectively relieve the glass from any undue strain. This is accomplished by giving to the threaded portion of the screw peg stem a pitch exactly equal to the pitch of the screw threads which are being formed on the article being 20 molded.

Due to the friction on the shafts 114 which support the worm wheels 113, the worm wheels during the screw out operation act as stationary nuts through which the screw out stem, function- 25 ing at this time as a lead screw, is retracted.

Prior to the commencement of the screw out operation, the parts of the press mechanism have been caused to assume the position illustrated in Figure 15 with the rod 133 against the roller 30 135, in which position there is sufficient clearance between the cross head 123 and the gear 121 to permit an unscrewing movement of the screw peg stem sufficient to completely disengage the screw peg 110 from the formed article. 35

Movement of the press mechanism into the position illustrated in Figure 15 is accomplished, prior to the screw out operation, by a suitable actuation of the press head valve within the casting 180 such as to connect the pipe 178 to exhaust and the pipe 179 to live pressure, the live pressure effecting a raising movement of the piston 132 to the extent permitted by the roller 135. Thereafter, the press head valve is again shifted into a neutral position in which live air 45 is cut off from both ends of the cylinder 134, and the air therein is trapped. This trapping condition exists at the time of the screw out operation just described.

Mold opening and closing

Cooperating with each of the press head mechanisms is a mold, all of which molds are of the same construction, whereby the description of one of the molds will suffice for an understanding of 55 the construction and operation of all of the molds provided for the machine. For purposes of this description reference may be had more particularly to Figure 10 of the drawings, in which the mold is shown as carried by openable mold halves 60 220 carried by a hinge pin 221. This hinge pin is supported at its lower end in a base plate P, and at its upper end in the intermediate frame f. One of these base plates is provided for each mold and is in turn secured to the mold table 54. 65

Projecting laterally from each mold half is a lug 222 to which is pivotally connected the outer end of a lever 223, the intermediate portions of which levers are carried by swinging fulcrums 225. These swinging fulcrums are in turn supported for swinging movement by the hinge pin 221. By reason of this construction, it will be apparent that by drawing the inner ends of the levers 223 toward each other, the outer ends will be swung away from each other to open the 75

5 mold halves, this open position being illustrated in dot and dash lines in the drawings. Such a movement is accomplished by the use of toggle links 226 pivotally connected to the inner ends of the levers 223, the toggle links being connected to the outer end of the piston rod 227 secured to piston 228 reciprocable within a mold opening and closing cylinder 229 carried by the base plate P.

10 Pressure fluid for operating the mold opening and closing mechanism is supplied by way of piping connections illustrated more particularly in Figures 20, 21 and 22, and including a pressure supply line 230 leading from the distributing member 166 to a mold cylinder valve 231.

15 The mold cylinder valves, corresponding in number to the number of molds, are conveniently carried by the intermediate frame f and project upwardly therefrom as clearly illustrated in Figure 5. Within each cylinder 231 is a valve, hereinafter described, from the upper end of which projects a stem 233 adapted to be manually operated at the will of the operator, and from the lower end of which projects a stem 232 adapted 20 to be automatically operated at predetermined times during the operation of the machine.

25 From the mold cylinder valve 231 to the rear end of the mold opening and closing cylinder 229 there is a connection 234 for supplying pressure fluid to the cylinder for forcing the piston 228 outwardly and moving the mold halves into the position illustrated in dot and dash lines in Figure 10. A second line 236 extends from the mold cylinder valve 231 to the front end of the 30 mold opening and closing cylinder 229 for moving the piston in the opposite direction and closing the mold halves. Provided in each of the lines 234 and 236 is a by-pass check valve 235, hereinafter described in detail, and manually adjustable for controlling the return or exhaust 35 from the mold opening and closing cylinder and thereby governing the speed of movement of the piston 228 in either direction.

40 In Figure 52 one of the mold cylinder valves is shown in detail, while in Figure 54 there is 45 illustrated one of the check valves 235.

45 For effecting automatic operation of the mold cylinder valve in predetermined timed relation to the other operations, there is provided a two-part cam comprising parts 238 and 238', the part 50 238 being mounted on the main base 50 of the machine, and the part 238' being carried by the take-out mechanism hereinafter described. Cooperating with this two-part cam is a cam roller 55 237 on the lower end of the stem 232. During a portion of the travel of the mold table the cam roller 237 rides over the portion 238 thereby raising the mold cylinder valve and admitting air by way of the line 236 to the outer end of the mold opening and closing cylinder 229 for effecting a closing movement of the mold halves 60 preparatory to a charging operation.

65 After completion of the charging operation and the pressing of the charge, the rotation of the table will be effective for bringing the cam roller 237 into engagement with the cam portion 238' under which it rides, and which is effective for lowering the stem 232, thereby shifting the mold cylinder valve and directing air through the connection 234 to the inner end of the cylinder 229 for opening the mold halves, preparatory to a taking-out operation. (See Figure 6.)

Take-out

75 The mechanism for removing a finished article

from a press mold is shown in Figures 26, 27 and 28. Each mold comprises a bottom plug 240 carried by a slide 241 substantially radially movable in guideways formed in the base plate P. This slide is provided with a rack 242 on its under side 5 with which cooperates a segmental gear 243 having a pivotal mounting 244 in a frame 245 supported on the under side of the mold table 54. Adjustment screws 246 are carried by the frame 245, and may be so adjusted as to limit the arc of 10 swinging movement of the gear segment 243.

15 The mold halves 220 having been opened by the mechanism above described, and particularly the portion 238' of the two-part cam, just previously to the arrival of a mold at the take-out position, 20 the plug 240 is moved outwardly by its slide through the operation of the segmental gear 243, this gear being actuated by cam mechanism disposed at this point and shown more particularly in Figure 26. This cam, which will later be described, together with the portions of the mechanism just referred to, are all supported by a sub-frame 251 cooperating with a slotted positioning member 250 mounted on the base 50.

25 Extending through the sub-frame 251 are bolts 252 the heads 253 of which are received within the slot in the positioning member 250. By loosening the bolts, the sub-frame 251 may be adjusted through a predetermined arc about the central axis of the forming machine, the extent of 30 adjustment being determined by the length of the slot in the positioning member 250. In order to insure proper arcuate movement of the support during adjustment thereof, the same may, as 35 illustrated in Figure 26, be bolted to a split ring 270 which surrounds the table support 52.

40 Carried by the sub-frame 251 is a cam 255 for operating the segmental gear 243 in one direction, this cam being pivoted at 256 to the sub-frame, and normally held in the position illustrated in Figure 26 by a compression spring 257. Provided in the sub-frame 251 is a slot 258 which cooperates with a bolt 259 projecting downwardly from the cam 255, for guiding the cam during its swinging movement and limiting both the amount of swinging movement and the normal position of the cam. In opposed relation to the cam 255 is a second cam 260 secured in fixed relationship to the sub-frame, but having a portion 261 carried by a pivot 262 in such position as to constitute a continuation 50 of the cam 260, but capable of yielding, in case of abnormal operation as hereinafter set forth, against the restraining influence of a spring 263. The pivoted portion 261 of the cam cooperates with a slot through a bolt construction similar to 55 that described for the cam 255, and clearly illustrated in Figure 26.

60 At its outer end, the sub-frame 251 carries the take-out supporting frame 271, within which frame is mounted a horizontally extending driving shaft 272 carrying at its outer end an eccentric 273 held thereon by a nut 274. For rotating the shaft 272 and thereby effecting operation of the take-out mechanism, there is provided on the under side of the mold table a ring gear 408 (hereinafter described), which meshes with a gear 276 65 keyed to the inner end of the shaft 272.

65 By reason of the construction just described, it will be apparent that the sub-frame 251 with its associated parts may be moved as a unit to any 70 desired position about the axis of the machine, the sub-frame maintaining the desired operative relationship of the parts during such movement. During such movement the desired driving relationship is maintained between the gear 276 and

the ring gear 408, since the gear 276 is free, during adjustment of the sub-frame, to roll around the ring gear. This is desirable, since the relationship of the gears 276 and 408 having been once 5 properly determined, it is maintained during the adjusting of the take-out sub-frame.

Slidable vertically in the take-out frame 271 is a slide 277, as illustrated more particularly in Figure 28, this slide being provided with spaced outwardly projecting rollers 278 which cooperate with diametrically opposite portions of the eccentric 273, whereby upon rotation of the eccentric the slide 277 is vertically reciprocated in the take-out frame. A rack 279 extends upwardly from the 10 slide 277, and meshes with the teeth of a pinion 280 keyed to a transverse shaft 281 supported in bearings 282 in the take-out frame.

Keyed to one end of the transverse shaft 281 is a hub 284 having an offset portion 284' as illustrated more particularly in Figure 28 through which project adjusting screws 285. These adjusting screws bear at their upper ends against pads 286 formed on a yoke 287 which encircles a portion of the hub 284 of reduced diameter and has an accurate fit thereon, the yoke being held against axial movement on the hub by a suitable washer and nut assembly 288. This construction enables the relative position of the yoke 287 and the hub 284 to be varied at will in one 25 direction or the other by suitable advancement or retraction of the adjusting screws 285.

Formed integrally with the yoke 287 is an outwardly projecting finger 287' formed with a pad to which is bolted or otherwise secured a safety 30 finger block 289. To the upper surface of the safety take-out finger block is secured a take-out finger plate 289' illustrated more particularly in Figure 26 and including spaced fingers separated a sufficient distance to receive therebetween the 35 article being formed by the machine.

The take-out finger plate 289' is of any special construction, as will be understood by those skilled in the art, and is comparatively expensive. In order to protect this finger plate, as well as other 40 parts of the machine, against injury in case of any abnormal operating conditions, the safety finger block 289 is preferably of special construction and material such that it will break in case the finger is brought into engagement either with an improperly shaped article or any body of glass 45 or other foreign material improperly positioned on or carried by the machine. The desired results in this particular may be accomplished by forming the safety finger block of aluminum having one or more grooves or weakened portions formed therein, as clearly indicated in Figure 27, whereby 50 cleavage or breakage planes are established.

As a mold approaches the take-out position, after having been opened in the manner described, and the bottom plug 240 starts its outward movement, the take-out mechanism starts swinging from the position illustrated in dotted lines in Figure 27 to the position illustrated in full lines, the mold plug and the take-out mechanism 55 completing their movements at approximately the same time, depending upon the initial adjustment of the machine. With the take-out finger plate in its full line position, continued travel of the mold table will move the insulator, or other formed article, into position between the fingers of the take-out finger plate, whereupon the slide 277 will commence movement in the opposite direction to reverse the rotation of the gear 280 and the take-out mechanism, thereby swinging 60 the take-out mechanism with the article sup-

ported thereby from the full line position to its dotted line position ready for delivery to a conveyor or other mechanism. Substantially simultaneously with the operation just described, the bottom plug 240 is retracted into position in which the mold halves may close therearound preparatory to a succeeding forming operation. 5

By reference more particularly to Figures 26 and 27 of the drawings, it will be apparent that during travel of the roller 243' on the extension of the segmental gear 243 along the portion of the cam 255 from substantially the point *a* to substantially the point *b*, the segmental gear will be swung in a counterclockwise direction as viewed in Figure 27, thereby moving the bottom plug 240 15 outwardly.

During travel of the roller from the point *b* to the point *c* the plug will be held in its outer position, this time interval being sufficiently long to insure firm engagement between the formed article and the off-take mechanism. Continued travel of the roller will bring it into engagement with the pivoted portion 261 of the cam 260, this cam being so shaped that travel of the roller thereover from approximately the point *d* to the 20 point *e* will be effective for retracting the bottom plug into its normal position.

In Figure 1 of the drawings the take-out mechanism is illustrated as having just commenced to lift a formed article from the machine, a series 30 of previously delivered articles being shown in side by side position on a conveyor C. When the article has been brought by the take-out mechanism to a position over the conveyor, the article may be discharged from between the fingers of the finger plate 289' by an ejecting mechanism 35 illustrated more particularly in Figure 26 of the drawings and comprising a cylinder 290 suitably supported by the conveyor frame, or in any other desired manner in such position that the piston rod 291 will have a reciprocable movement substantially in line with the direction of extension of the fingers of the off-take finger plate 289'. This piston rod carries at its outer end a fork 292 40 for engaging the article and ejecting the same 45 from the finger plate so that it is free to drop onto the conveyor. The fork 292, which may be of any desired material, is preferably provided with an asbestos covering over that portion which comes into engagement with the formed article. 50

For effecting actuation of the piston (not shown) secured to the piston rod 291, the cylinder 290 is provided at one end with a flexible connection 293 to the port 294 in an ejecting valve casing 295 and with a second flexible connection 296 to a port 297 in said casing. Reciprocable within the casing 295 is a valve 298 for controlling the supply of pressure fluid to and exhaust of the fluid from the opposite ends of the ejecting cylinder 290, the connections 293 and 296 being provided with check valves 235 of the character before referred to and hereinafter described in detail, whereby the rate of movement of the ejecting mechanism may be accurately controlled. 55

Movement of the valve 298 is controlled by a 60 lever 299 pivoted at 300 to an arm 301 projecting outwardly from the take-out frame 271. A roller 302 is mounted beneath the lever 299 in position to cooperate with a cam 303 formed on the eccentric 273, this cam being effective for oscillating the lever 299 and reciprocating the valve 298 against the action of its retaining spring 298'. 65

The ejecting valve cylinder 295, in addition to the ports 294 and 297, is provided with a main supply port 304 normally connected to a source of 70 75

air under pressure, and with an exhaust port 305 for the cylinder 290 during the retracting movement of the ejector and with a second exhaust port 306 effective during the ejecting movement of the ejector. In Figure 26 the parts are illustrated in such position that air under pressure passes from the connection 304 through the annular space 307 around the valve stem to the port 297 and thence by way of the flexible connection 296 to the back end of the cylinder 290, whereby the ejector is moved outwardly for ejecting an article from between the fingers of the finger plate 289.

At this time the line 293 is open to exhaust by way of the port 306 by means of the annular space 308 around the valve stem. Upon completion of the ejecting operation, the cam 303 will have passed out of engagement with the roller 302, thereby permitting the spring 298' to move the valve 298 to the right as viewed in Figure 26, in which position the port 297 will be connected to the exhaust port 305 through the annular space 307, while the port 294 will be connected to the live air line 304 through the annular space 308. In such position, the back end of the cylinder will be permitted to exhaust, while air under pressure will pass through the connection 293 for retracting the ejector. The actuation of the ejecting valve will occur in timed relation to the operation of the machine, as will be readily apparent.

In Figure 26 of the drawings the various ports to the ejecting cylinder 295 are all illustrated as being in one plane, for purposes of a clearer understanding of the operation of the valve. It is to be understood, however, that the exact position of these ports may be varied in any desired manner to facilitate the making of the desired pipe connections thereto, the actual position of the ports being accurately illustrated in Figure 5 of the drawings.

40 Fluid pressure system

In Figure 20 of the drawings, there are disclosed diagrammatically the various fluid pressure connections by means of which the operations of the various fluid pressure motors are obtained, and the cooling of the screw peg and the application of dope thereto effected.

The operations mentioned are preferably effected by means of air at three different pressures. This air is delivered (see Figure 1) through a suitable pressure supply line A to a series of pressure regulating valves V. These valves in turn control the pressure conditions in a high pressure line H, a medium pressure line M and a low pressure line L. (Figure 20.) These three pressure lines are in turn connected to the stationary inner member 166' of the distributing valve, the distributing valve structure being illustrated in detail in Figures 49 and 50. The inner member is constructed to provide a high pressure chamber h, a medium pressure chamber m and a low pressure chamber l. These pressure chambers have discharge ports h', m' and l', respectively, communicating with grooves h², m² and l² formed in the distributing member 166. The grooves and ports are so arranged that during operation of the machine, the high pressure port h' will be continuously in communication with the high pressure groove h², the medium pressure port m' in communication with the medium pressure groove m², and the low pressure port l' continuously in communication with the low pressure groove l², whereby the grooves will have pressure conditions continuously maintained therein of the

nature determined by the respective pressure supply means.

In Figure 20 there is illustrated one of the press mechanisms in elevated position. Movement to this position is accomplished by shifting of the valve stem 175 of the press head cylinder valve into the position shown in Figure 20. At this time, high pressure air passes from the high pressure groove h² through the line 177 into the press head cylinder valve casing 180. With the valve 10 in the position shown, an annular groove h³ establishes communication between the connection 177 and the connection 179 leading to the valve assembly by means of which air pressure is admitted to the lower end of the press head cylinder 134, this pressure being effective for moving the piston therein into its upper position. At this same time, the upper end of the cylinder is permitted to exhaust through the upper valve assembly into the connection 178 and thence by way 20 of an annular groove h⁴ into the exhaust port h⁵. This exhaust port may communicate freely with the atmosphere, or may be piped to any desired point, as will be well understood.

As illustrated in Figure 20, and in detail in Figure 51, wherein the press head valve is illustrated in greater detail, there may be provided a suitable detent or pawl for maintaining the valve in either extreme to which it is shifted under the influence of the roller 176. The outer end of the valve stem 175 is provided with a knob 175', which may be grasped by the operator for manual operation of the valve.

In Figure 51, the valve is shown in its opposite position from that illustrated in Figure 20, at which time air under pressure may pass from the connection 177 by way of groove h⁴ into the connection 178 and thence to the valve assembly 30 cooperating with the upper end of the press head cylinder. At this time, the exhaust from the lower 40 end of the cylinder will be delivered through the lower valve assembly into the connection 179, and thence by way of groove h³ into the exhaust connection 195, previously described, for effecting a "dope" application to a succeeding screw peg. 45

When the valve is moved to its neutral position by means of the cushioning cam 327 (later to be described), the enlargement on the valve stem intermediate the grooves h³ and h⁴ will cover the pressure supply line 177, while the enlargements adjacent either end of the valve stem will cover the respective discharge ports, whereby the supply of pressure into the cylinder and the discharge of pressure therefrom will be prevented, thus maintaining the press head piston in its intermediate position as desired during the screw-out operation.

The connection 230 communicates at one end with the medium pressure groove m², and at its 60 opposite end with a suitable port m³ in the mold cylinder valve 231. In Figure 20, the valve is illustrated as being in its upper position, under the influence of the cam 238. In this position, air is permitted to pass from the port m³ by way 65 of the groove m⁴ into the connection 236 leading to the front end of the mold cylinder 229 for effecting travel of the piston inwardly and thereby closing the mold halves 220. During such movement of the piston within the mold cylinder, 70 the air from the opposite end of the cylinder is discharged through the connection 234 around the mold cylinder valve by way of a groove m⁵ to one or more discharge ports m⁶. The rate of discharge is controlled, as before described, by means 75

of a check valve 235, one of which is illustrated in detail in Figure 54. The construction of this valve is such that the ball check therein may be freely unseated during passage of air into the cylinder, but seats when air is exhausting from the cylinder. Accordingly, air may flow in only one direction past this ball check. A manually adjustable valve element 235' of the globe type is therefore effective, in accordance with its initial setting, to regulate the rate of exhaust of air from the cylinder. A more complete explanation of the function of such a valve mechanism has been given above, in connection with the description of the check valve assembly 181.

15 In Figure 52, the mold cylinder valve 231 is illustrated in its lower position as brought about by the cam 238'. In this position, air under pressure passes from the port m^3 by way of groove m^5 into the connection 234 for moving the piston outwardly and opening the mold halves 220. At this time, air is permitted to exhaust from the front end of the cylinder by way of the connection 236, check valve 235 and groove m^4 to the exhaust ports m^7 .
 20 The connection 304 for supplying air to the ejecting valve 298 may receive its supply of air under pressure directly from either of the lines H or M, it being illustrated in Figure 20 as connected to the medium pressure line M. The construction and operation of this valve have already been described in detail in connection with the take-out operation.

30 While Figure 20 illustrates only one of the press mechanisms and one of the mold operating mechanisms, it will be understood that the connections shown from the distributing member outwardly are duplicated for each of the press heads and each of the molds, with the exception of the connection l^3 which supplies low air pressure from the low pressure groove l^2 to the annular chamber 202. But one of these connections is requisite, although if the volume of cooling air used is large, a plurality of connections l^3 properly distributed about the axis of the machine may be provided. Communicating with the annular chamber 202, however, is a separate connection 203 for each of the mold cooling valves 204. One of these valves 204 is illustrated in Figure 53 in its lower position, while the same valve is illustrated in Figure 20 in its upper position.

40 As illustrated in Figure 20, the groove l^4 in the valve is out of registration with the lines 203 and 203a, whereby the only air which is permitted to pass to the interior of the screw peg is by way of the by-pass connection 213. As soon, however, as a press head starts its downward movement, the adjustable stop 206 moves out of engagement with the valve stem 205, whereupon the valve is moved from the position illustrated in Figure 20 into the position illustrated in Figure 53 under the influence of the compression spring surrounding the valve stem. This movement brings the port l^4 to registration with the connections 203 and 203a, whereby a supply of cooling air to the screw peg is permitted. This cooling continues so long as the press head is in lowered position. Accordingly, the screw peg is supplied internally with cooling fluid just prior to a pressing operation, all during the time the peg is in contact with the glass, during the screw out operation, and continuously until raising movement of the press head is substantially completed.

Cams

5 It will be understood by those skilled in the art that a machine of the character herein contemplated must be capable of operation on glass gathers of a wide variety of different sizes and weights in order to give a sufficient flexibility of operation to make the machine commercially practicable. In actual practice, however, certain adjustments are ordinarily required each time a change is made in the characteristics of the charge, or article being made, and the present machine is designed to permit the making of the necessary adjustments so as to enable the desired range of articles to be produced.

10 A certain adjustment having been determined upon, however, for the most satisfactory operation it is desirable that successive articles being formed shall all be subjected to forming operations not only in the same definite sequence 20 but in the same relative time intervals. From the standpoint of practical expediency, the point of charging, as illustrated in Figure 6, is usually more or less fixed by the location of the furnace and/or the feeding mechanism. After the mold 25 passes the charging point where it receives its charge of glass, it is desirable that the press head mechanism shall be lowered at a definite predetermined time interval thereafter, this time interval having been initially accurately determined. As shown in Figure 8, a cam support 310 is keyed to the center column 156 either directly or through the medium of an intermediate bushing 310'. If the size of the ware 30 being produced is large, it is desirable that the press head lowering operation should be delayed, while if the ware is small, the operation should be advanced. For ordinary ware, the timing of the press head lowering is controlled by a cam 311 shown in full lines in Figure 8.

40 A cam 312 is shown in dot and dash lines at the right of the cam 311 to indicate the position of a cam which might be substituted for the cam 311 if the ware being produced is small, while a third cam 313 is shown in dot and dash lines at the left of the cam 311 to indicate a cam 45 which might be used for relatively larger ware. Since the cam support 310 is fixed relatively to the center column of the machine, the proper press head lowering cam having been determined upon and secured to the cam support, it 50 will be effective for initiating the lowering movement of successive press head mechanisms at definite predetermined time intervals.

45 As is shown in Figure 5 of the drawings, a cylindrical driving member 315 extends upwardly within the center column 156 of the machine and carries at its upper end a pinion 316, and at its lower end a worm wheel 317. A spur gear 318 keyed to a shaft 319 meshes with the pinion 316. 60 The shaft 319 is rotatable within a bearing 320 (see Figure 7) afforded by an adjustable cam plate 321. To the lower end of the shaft 319 is secured a gear 322 (see Figure 5) which meshes with an internal gear 324 carried by a bottom disk 325. This disk rests upon a shoulder on the center column 156, and is so secured to the center column as to be held against rotation. Accordingly, when the worm wheel 317 is driven, the gears 318 and 322 move orbitally about the axis 70 of the forming machine, carrying the cam plate 321 therewith.

75 A second adjustable cam plate 342 surrounds the upper end of the center column 156. The stationary cam support or cam plate 310, and the 75

movable cam plates 321 and 342 are provided with interleaved hub portions 343, 344 and 345, respectively, these hubs functioning similarly to the usual hinge plate structure for supporting the plates. A shaft 347 is mounted in a bearing 348 afforded by the cam plate 342. A gear 349 is secured to the upper end of the shaft 347, and meshes with a pinion 350 secured to the upper end of a central shaft 351 extending longitudinally and concentrically within the cylindrical driving member 315. A worm wheel 352 is secured to the lower end of this central shaft 351.

To the lower end of the shaft 347 is secured a gear 322' which, similarly to the gear 322, meshes 15 with the internal gear 324 to effect orbital movement of the gear 349. Either the cam plate 321 or the cam plate 342 may, accordingly, be swung in opposite directions about the center column of the machine upon producing orbital movement 20 of the gears 322 and 322' as before described.

In Figures 13 and 14 of the drawings there is shown mechanism for effecting rotation of the worm wheels 317 and 352. This mechanism includes a gear casing 1355 carried by the base 50 25 and housing such worm wheels. A worm 1356 in mesh with the worm wheel 317 is secured to the inner end of a shaft 1357 extending substantially radially beneath the base 50. At its outer end is secured a hand wheel 1358. A second worm 1359, 30 in mesh with the worm wheel 352, is secured to the inner end of a second shaft 1360 extending substantially parallel with the shaft 1357.

A gear 361 is rotatably mounted on the shaft 1360 adjacent its outer end. This gear is in mesh 35 with a gear 1362 secured to the shaft 1357. Feathered to the shaft 1360 is a clutch member 1364. This member is formed with a clutch surface which, when pressed against a cooperating clutch surface formed on the gear 361, provides a frictional driving connection between such clutch member and the gear 361. A spring 1365 is interposed between these parts in such manner as to normally effect outward or disengaging movement of the clutch member 1364. Rotation of the shaft 45 1360 may be secured by means of a second hand wheel 1366.

It will be apparent to those skilled in the art that the hand wheel 1358 may be turned to rotate the cylindrical driving member 315 adapted to 50 shift the position of the cam plate 321. With the clutch member just described disengaged, the hand wheel 1366 is adapted to rotate the worm wheel 352 and effect a shifting movement of the cam plate 342. If, however, the clutch member is 55 forced inwardly, simultaneous adjustment of the two cam plates 321 and 342 will be effected. This operation may be desirable under certain conditions where an effective timing relationship has been established between the two cam plates, 60 which relationship it is desired to maintain during subsequent operations, which operations are either advanced or retarded in a given cycle by advancing or retarding the two cam plates as a unit.

In case it is desired to lock the clutch member in such engaging position that simultaneous rotation of the two cam plates is obtained, there may be provided a nut 1367 cooperating with a threaded portion of the shaft 1360 for moving the clutch 65 member 1364 into engagement with the gear 361 and frictionally holding these two parts in engaging relationship.

The outer end of the adjustable cam plate 342 is shaped to form a press head initial lifting cam 70 75 353, this cam being designed to move the press

head valve cam roller 176 in the direction opposite to that which it is moved by the press head lowering cam 311 carried by the cam plate 310. As the molding mechanism revolves about the center column, the press mechanism descends due, 5 to the admission of air above the press piston 132, such air admission being controlled by the action of the press head lowering cam 311 on the press head valve roller 176. By the time this roller has reached the press head initial lifting cam 353, 10 the glass has been forced into the various parts of the mold cavity so as to form the body of the insulator, the portion surrounding the screw peg and the skirt.

The press head initial lifting cam causes air to 15 enter the lower end of the press head cylinder 134 and raise the piston 132 therein to the extent permitted by the roller 135 carried by the slide block 131, which roller at this time is in such position as to directly overlie the upper end of the rod 133 20 projecting upwardly from the press head piston. The relationship of the parts is such that the amount of this upward movement is sufficient to permit subsequent unscrewing of the screw peg 110 to an extent sufficient to effect its disengagement 25 from the molded glass. This operation is permitted by so dimensioning the parts that with the upper end of the rod 133 in engagement with the roller 135, the clearance between the cross head 123 and the upper surface of the gear 121 30 will be slightly greater than the amount of vertical movement necessary to effect the screw out operation.

Further rotation about the center column brings the press head valve roller 176 into contact 35 with a cushioning cam 327 detachably secured to the adjustable cam plate 321. This cushioning cam is of such construction that it does not effect a complete reverse movement of the press head valve, but merely moves the same 40 into a neutral or intermediate position, in which position it is effective for trapping the air in the opposite ends of the press head cylinder 134, thereby tending to prevent movement of the piston 132 in either direction.

Simultaneously with the movement of the press head valve into neutral, and therefore a quasi press head locking position, a screw out tripper cam 329 formed on the adjustable cam plate 321 engages a tripper roller 333 to effect a shifting 50 movement of the screw out clutch member 169. The tripper roller 333 is secured to the upper end of an arm 332 projecting upwardly from a tripper fork 330 pivotally mounted to the upper frame F. This tripper fork is provided with spaced 55 lugs 331 projecting outwardly so as to lie on opposite sides of an abutment on the tripper 170. The inner end 335 of the tripper fork is in the shape of a spear head, the sharpened end of which is adapted to cooperate with a spring actuated latch 336 to insure quick shifting of the clutch member 169 either into or out of engagement with the teeth on the gear 167, it being apparent that the action of the spring latch is such that as soon as the tripper fork passes its intermediate position it is snapped to the extreme limit of movement in one direction or the other. The screw out tripper cam 329 is so shaped and positioned as to insure a screw out engagement 60 of the clutch 169 in proper timed relation to the other operations, this engagement, as before pointed out, occurring substantially concomitantly with the movement of the press head valve into neutral cushioning position.

Continued movement of the machine will cause 75

the tripper roller 333 to come into engagement with a screw out release cam 329', also carried by the adjustable cam plate 321. The construction of the screw out release cam is such as to effect movement of the tripper roller 333 in the opposite direction to that effected by the screw out tripper cam 329, to thereby disengage the clutch member 169 and interrupt further screw out movement. To this end the circumferential distance between the screw out tripper cam 329 and the screw out release cam 329' is obviously such as to only permit the screw clutch member 169 to remain in engagement with the gear 167 for such a period of time as to effectively accomplish the desired unscrewing of the screw peg 110.

The screw out operation having been concluded, continued operation of the machine will bring the cam roller 140 into engagement with a high point 340' on a slide release cam 340 carried by the adjustable cam plate 321, the high point 340' being spaced circumferentially but a short distance from the screw out release cam 329' so that almost immediately upon completion of the screw out operation, the slide 137 with its roller 135 is retracted to permit upward movement of the press head mechanism at such time as the press head valve is moved from its neutral or cushioning position into such position as to admit air to the lower end of the press head cylinder 134. This movement is effected by the action of the high point 353' of the press head lifting cam 353a, this high point being effective on the press head roller 176 for shifting the press head valve to such position that air is admitted to the lower end of the press head cylinder.

It will have been noted that the press head initial lifting cam 353 is supported by a cam plate 342 which is movable separately from the cam plate 321. It is therefore possible, by relative adjustment between these two cam plates, to change the time relation between the termination of the pressing operation and the commencement of the screw out operation. The pressing operation itself may, of course, be lengthened or shortened as the press head initial lifting cam 353 is moved in one direction or the other relative to the press head lowering cam 311.

The cam plate 321 carries a plurality of cams, since the several operations controlled thereby preferably have a fixed time interval between them. The first of these operations, as before described, is to move the press head valve into neutral position, this being accomplished by the cushioning cam 327 concomitantly with the operation of the screw out tripper cam 329 which constitutes the screw out operation. Succeeding this operation, the screw out release cam 329' becomes effective for unclutching the screw out mechanism to stop further rotation of the screw peg 110. Thereafter the high point 340' of the slide release cam 340 becomes effective for releasing the press head mechanism to permit further upward movement thereof. The final operation is that of raising the press mechanism, which is accomplished by the high point 353' of the press head lifting cam 353a. Although the time interval between any one of these operations and the next succeeding operation is fixed, the time at which the entire group of operations takes place with respect to the entire cycle of the machine may be easily altered by shifting the cam plate 321.

Other cams may be substituted in place of the screw out release cam 329', the slide release cam 340, and the press head lifting cam 353a in a

manner similar to that in which either the cam 312 or the cam 313 may be substituted for the press head lowering cam 311. Such a substitution may be desirable in case the machine is to be driven at a relatively higher speed. In Figure 8 of the drawings, there is shown in chain lines a screw out release cam 329a which may be substituted for the screw out release cam 329'; a slide release cam 340a which may be substituted for the slide release cam 340, and a press head lifting cam 353b which may be substituted for the press head lifting cam 353a. The substitution of this second group of cams gives a slightly greater interval between the starting of the screw out operation and completion thereof together with a correspondingly greater time interval between the starting of the screw out operation and the release of the slide 137 and the final raising of the press head mechanism.

As a safety measure, the cam plate 310 is provided with a release safety cam 340b which is provided to insure retraction of the slide 137 in case, by any chance, the press head mechanism shall have reached the point of the safety release cam with the parts in such position that the roller is holding the press head mechanism in its down position. It is obvious that at this point live air is being admitted to the lower end of the press head cylinder 134 since the press head lifting cam 353a has functioned for this purpose. Therefore, upon retraction of the slide 137, upward movement of the press head mechanism is insured before the press head reaches the charging point so indicated on Figure 6. This condition, while it will not obtain during normal operating conditions, may exist in case the machine is being rotated by hand for any purpose and in case during such rotation an operator has manually moved a head into its lower position so that the roller 135 has been permitted to move over the upper end of the rod. It will therefore be apparent that the main function of the safety release cam 340b is merely to insure proper positioning of the press head parts in case they have been manually moved from the position which they would normally occupy.

Operation of the forming machine

Since the feeding mechanism is driven by the main driving mechanism for the forming machine, the description of the operation of the feeding mechanism will be postponed until the driving mechanism is described. The forming machine, as thus far described, is particularly well adapted to the production of glass insulators, although it is understood that by making the necessary changes in the configuration and movement of the cooperating forming parts, the machine is adaptable to the production of other articles. The mold table 54 is continuously rotated during all normal operating conditions, and the various operations described take place during the travel of the machine.

Just prior to the time that a mold reaches the charging point, as indicated for example in Figure 6, the cam 238 shown at the lower left hand portion of Figure 5 engages the cam roller 237, and the mold cylinder valve is moved into such position as to effect closing of the mold halves. At the charging point a charge of glass is delivered to the mold. The press head valve roller 176 is thereupon engaged by the press head lowering cam 311 (or cam 312 or 313 under conditions such as referred to) so that fluid is delivered to the upper end of the cylinder 134 to

move the press head mechanism downwardly. The speed at which such movement takes place is controlled by adjustment of the valve 192 relative to its port 191 (Figure 18). As the piston 132 reaches the lower limit of its travel, the roller 135 is forced outwardly by its spring so as to be in such a position that when the press head initial lifting cam 353 comes into operation the press head mechanism can only be given a limited 10 upward movement as before described. Thereafter the cushioning screw out release, slide release and press head lifting operations occur in the sequence set forth. The rate at which the press head mechanism is elevated is likewise controlled by the relationship between the valve 192 and its port 191 in the upper valve assembly.

As the mold with the formed article therein nears the take out position, the cam portion 238' engages the roller 237 and shifts the mold cylinder valve in such manner as to effect delivery of air into the inner end of the mold cylinder 229. This causes the mold halves 220 to separate. The cam 255 thereupon causes the segmental gear 243 to move the rack 242 outwardly so that the bottom plug 240 of the mold projects a formed article into position to be engaged by the take out mechanism. The engaging and holding finger plate 289' is intermittently oscillated, as set forth, and at the time the article is in its outer 30 position the finger holding plate is so positioned as to engage the insulator on the bottom plug. The take out mechanism thereupon swings through 180° and the ejecting motor 290 moves the forked ejecting member 292 into engagement 35 with the insulator to cause the same to drop upon the conveyor C, which may transfer the same to a leer or any other desired point.

In the meantime, the mold table has continued to travel onwardly, and the cam portion 261 has come into operation to shift the mold bottom plug inwardly to its normal position. The cam 238 will thereupon become effective at the proper time interval, as illustrated in Figure 6 of the drawings, to shift the mold cylinder valve so as to supply air to the mold cylinder 229 to close the mold, the latter then being ready for another cycle of operations.

Inasmuch as the cam portion 238 is carried by the main base of the machine, while the cam portion 238' is carried by the sub-frame of the take out mechanism, the relative adjustment which is effected between these parts produces automatically a corresponding adjustment as required of the different cam portions.

Attention has already been directed to the fact that the supply of pressure fluid which constitutes the lowering of the press head mechanism is controlled by a cam the position of which cannot be adjusted during operation of the machine. It has also been pointed out that the rate at which the press mechanism moves in both directions may be effectively controlled by the operator by proper adjustment of valves provided for that purpose. The adjustment of the cam plates 321 and 342 either simultaneously or one relatively to the other gives a desirable range of timing such that a wide variety of different articles of different weights and characteristics may be effectively produced.

The operation of the cooling devices has already been described in detail, and the operation of the safety release cam 340b has been set forth. The operation of the various other safety devices, shown more particularly in Figures 38 to 41, inclusive, will be described in connection with the

control mechanism for the main drive of the machine.

Drive

In Figures 30, 31 and 32 is shown a main driving motor E for driving both the forming machine and the feeding mechanism. In the embodiment illustrated herein, this motor is shown as being an electric motor, and therefore has suitable control circuits illustrated more particularly in Figures 46 and 47, although it is obvious that other types of prime movers may be substituted.

The driving motor is supported on the main base 50 of the machine. The machine having been properly located in correct relation to other apparatus with which it is designed to cooperate, the device shown in Figure 29 is operated to bring a foot 354 into engagement with the floor of the shop. A screw shaft 355 is provided within a suitable housing secured to the main base 50. This screw shaft is formed intermediate its ends with a collar between which and the shaft casing is provided a ball-thrust bearing 356. A sleeve 357 is reciprocable within the casing, its lower end being formed as a rounded abutment 358 and engaging in a socket 359 formed in the foot-piece 354. The sleeve 357 is internally threaded to engage threads on the shaft 355. The upper end of this shaft is provided with a squared portion 360 adapted to receive a crank, wrench, or the like, whereby the sleeve 357 may be raised or lowered as will be perfectly obvious.

The outer end of the motor shaft is provided with a solenoid brake 362 which is automatically applied when the current is cut off from the motor. The circuits for controlling this solenoid brake will be later described. To the other or inner end of the motor shaft is secured a combination gear comprising a bevel gear 363 and a pinion 364, the pinion conveniently surrounding the hub of the bevel gear and being secured thereto for simultaneously rotating therewith. The bevel gear meshes with a bevel gear 364' secured to the shaft of a switch 365, which may be of any desired type and construction such, for example, as a well known Carpenter switch. This switch controls the supply of current to a portion of the control circuits described in connection with the other control mechanisms for the motor. It is sufficient at this point to note that the motor driven switch 365 is opened as soon as the motor is started and closed when the motor is de-energized.

A spur gear 366 meshes with the pinion 364, this gear being secured to one end of a clutch shaft 367, having secured to its other end a pinion 368. A shaft 369 (see Figures 31 and 33) is mounted co-axially with the clutch shaft 367. The shaft 369 is rotatably supported at one end in the hub 370 of a rotatable gear casing 371. Jack shafts 372, preferably three in number, are rotatably supported in bearings provided by the casing 371, and extend lengthwise of the casing in substantially parallel relationship to the clutch shaft 367 and the shaft 369, the jack shafts being equi-distantly spaced in concentric relation to the clutch shaft. To each of these jack shafts is secured a small gear 374 and a large gear 375. Meshing with the small gears 374 is a center gear 376 secured to the shaft 369, while meshing with the large gears 375 is a second center pinion 368 splined to the clutch shaft 367.

With the construction just described, if the casing 371 is held stationary, the motor E through pinion 368 and the trains of gears 375, 374 and 75

376, drives the shaft 369 at a speed lower than the speed of the clutch shaft 367. This is obviously true, as during such a driving operation there is an initial speed reduction between the center pinion 368 and the large gears on the jack shafts 372, and a second speed reduction between the small gears on the jack shafts and the center pinion 376. If, however, the casing 371 is locked to rotate with the clutch shaft, the gears 368, 10 375, 374 and 376 are held against relative rotation, and the shaft 369 is accordingly driven by the motor E at the speed of the clutch shaft. For the purpose of thus locking the gear casing 371 to the clutch shaft, I provide a clutch shoe 380 15 keyed at 381 to the gear casing 371. In order to hold the clutch shoe 380 against rotation, slots 382 are formed in the periphery thereof in such position as to be engageable by a pin 383 actuated by mechanism later to be described. A cone 20 clutch 384 is feathered at 385 to the clutch shaft. A shipper 386 cooperates with a groove in the outer end of the cone clutch to effect movement thereof axially of the clutch shaft. When the cone is forced inwardly, its periphery engages 25 a friction surface on the interior of the clutch shoe 380, and the gear casing 371 is accordingly locked for rotation with the clutch shaft, the pin 383 at this time being in the position illustrated in Figure 32 out of engagement with any of the 30 slots 382.

The casing 371 may be mounted for rotation on ball bearings 387 supported in the housing K. Keyed to the shaft 369 adjacent the hub 370 in the casing 371 is a bevel gear 390 meshing 35 with a similar gear 391 formed integrally with a sleeve 392, this sleeve being journaled on a stud 393. A spur gear 394 also formed integrally with the sleeve 392 meshes with the gear 155 secured to the shaft 150 before described, and illustrated 40 in Figure 5 of the drawings.

To the outer end of the shaft 369 (see Figure 33) is secured a change speed pinion 396 meshing with a gear 397 keyed to a worm shaft 398 (see Figure 35). The gears 396 and 397 are hereinafter referred to as change speed gears for the reason that by effecting a proper substitution for the gears shown, of gears of different sizes, the relative speeds of the shafts 369 and 398 may be varied at will.

50 On the worm shaft 398 is a worm 400 meshing with a worm wheel 401 rotatably supported on a table drive shaft 402. The hub 403 of the worm wheel 401 is provided with a clutch tooth 404 (Figure 33). A shiftable clutch member 405 is 55 splined to the table drive shaft 402, and is provided with a clutch tooth 406 which, when in engagement with the tooth 404, causes driving of the table shaft 402 and therefore of the bevel gear 407 meshing with a ring gear 408 carried 60 on the under side of the table 54. Thus with the main drive clutch just described in engagement, the table is rotated by the motor.

To the outer end of the worm shaft 398, to which the change speed gear 397 is keyed, is 65 connected a feeder drive shaft 411, the feeder drive shaft in reality constituting an outward continuation of the worm shaft so as to rotate in unison therewith, although it will be understood that any suitable type of driving connection, 70 either flexible or otherwise, may be employed. To the outer end of the feeder drive shaft is secured a bevel gear 412 (see Figure 34). An intermediate shaft 413 is arranged co-axially with the shaft 411, and carries a bevel gear 414 for 75 driving a similar gear 415 shown in Figure 3 as

being secured to the lower end of the vertically extending shaft 100, so that when the shaft 413 is rotated, the shaft 100 will likewise be driven.

An adjustable casing 416 is supported by trunnion bearings 417 journaled in the differential 5 housing 98. Secured to and extending around the adjustable casing 416 is a gear 418 adapted to be rotated by a pinion 419 secured to an adjusting shaft 420 extending through the differential housing and carrying at its outer end a hand wheel 10 421 whereby the desired adjustment may be effected.

Extending radially of the casing 416 is a plurality of studs 423 disposed in a common plane, and each carrying at its inner end an intermediate gear 425 meshing respectively with the bevel gear 412 on the feeder drive shaft and with a second gear 426 on the shaft 413. If the casing 416 be held stationary, the feeder drive shaft 411 rotates the shaft 413 through the bevel gears 425 20 in the opposite direction, but without speed change. If, during the rotation of these shafts, the hand wheel 421 be rotated, the shaft 413 will be slowed down or speeded up relative to the feeder drive shaft, depending upon the direction 25 in which the hand wheel is rotated. This mechanism therefore constitutes a differential of generally standard characteristics constituting an adjusting and timing means for the feeder per se relative to the forming machine, inasmuch as the 30 feeder mechanism may be advanced or retarded relative to the forming machine with the parts in operation, thereby enabling adjustments to be made for the characteristics of the glass and the sizes and shapes of the gathers, as well under- 35 stood in the art.

To the opposite end of the worm shaft 398 is keyed a pinion 428 meshing with a pinion 429 keyed to a trip mechanism drive shaft 430. A clutch member 431 (Figure 32) is splined to the trip mechanism drive shaft 430, and is urged against a collar 432 by a spring 433. A second shiftable clutch member 434 is splined to a hollow shaft 435. Cooperating with the clutch member 434 to move the same longitudinally of the hollow shaft is a clutch shifter 438, whereby engagement of the two clutch members may be effected for driving the hollow shaft. This clutch shifter is provided with an extension 440 formed with a bore in which is received the clutch locking pin 50 383 normally urged outwardly into the position illustrated in Figure 32 by a spring 441. When the shifter 438 is moved to the left as viewed in this figure, the pin 383 will engage one of the slots 382 in the clutch shoe and hold the same 55 against rotation, the clutch members 431 and 434 at this time being in engagement so that the hollow shaft 435 is rotated.

Formed on the hollow shaft 435 is a worm 443 (see Figure 36), meshing with a worm wheel 444 60 rotatably mounted on a vertical shaft 445. A vertical trip pin 446 is slidably received within the worm wheel 444, a spring 447 pressing the trip pin toward its lowermost position. A trip cam 450 is formed on the base of the drive housing in such position that during rotation of the worm wheel 444 in the direction of the arrow in Figure 32, the trip pin is caused to ride upwardly onto and over the trip cam. As the worm wheel nears the end of one complete revolution, the trip pin engages 65 a lever arm 451 of a trip lever 452 secured to the vertical shaft 445. This trip lever is provided with forks 453 for engaging opposite sides of the clutch shifting member 386. The outer end of the lever arm 451 is sharpened or pointed, as in- 70 75

dicated at 454, to cooperate with a roller 455 carried by a slide 456 pressed inwardly by a spring 457. Due to this construction, it will be apparent that movement of the trip lever brings the 5 pointed end 454 into engagement with the roller 455, so that when the pin passes the center of the roller, the roller will snap to its extreme position thereby forcing the trip lever into its extreme position in the opposite direction and producing a 10 quick throw or snap action of the trip lever.

The clutch shifting member 386 has a rearwardly projecting arm 458 to which is pivoted a link 459. The other end of this link is pivotally connected to the clutch shifter 438. It will be 15 apparent therefore that starting with the shafts 430 and 435 clutched together, as indicated in Figure 37, the worm wheel 444 will be rotated for nearly a complete revolution or until such time as the trip pin 446 has been moved upward- 20 ly by the trip cam 450 to bring its upper end into engagement with the lever arm 451. This will cause the right hand fork 453 to engage the clutch shifting member 386 and move the same to the left into the position shown in Figure 32. 25 This movement brings the cone 384 into engagement with the clutch shoe 380 to produce high speed driving of the forming machine, and simultaneously moves the pin 383 out of contact with the teeth 382. Obviously, the shafts 430 and 435 30 are disconnected simultaneously with the withdrawal of the pin 383, the parts being interconnected for this purpose.

From the foregoing description, it will be apparent that starting with the parts in the position illustrated in Figure 37, the machine will be driven at slow speed through the reduction gearing provided for this purpose and located in the housing 371. After a predetermined period of such slow speed rotation, the automatic trip 40 mechanism will be actuated, independently of any act on the part of the operator, for shifting the cone clutch and thereby establishing such a driving relationship of the parts that the table will be rotated at high speed. There is 45 thus secured a condition of slow speed drive for a predetermined period effective for overcoming the friction of rest, which period of slow speed drive is followed by the normal high speed operating condition.

50 Automatic control and pilot lights

The motor E, where an electric motor is used, is conveniently of the alternating current induction type. In Figure 47 there are shown main 55 alternating current power lines 601, 602 and 603. An automatic overload safety mechanism 604 is provided for preventing burning out of the motor or of the other devices supplied with current from the power lines. Any suitable type of overload mechanism may be employed, this mechanism herein being shown diagrammatically as including induction coils for supplying induced current to a circuit including heating elements. If sufficient expansion of the heating elements 65 takes place, due to their being raised to too high a temperature, a switch 605 is opened. As will be later explained, this switch 605 is in series in a circuit which controls a main switch solenoid 606 arranged to open and close the main 70 switch 607. The main switch 607 comprises four bars, of which three connect and disconnect the lines 601, 602 and 603 to the motor leads 608, 609 and 610, respectively.

The armature shaft of the motor projects at 75 both ends, one end carrying the gears 363 and

364, as fully described in connection more particularly with Figure 30 of the drawings, the gear 363 meshing with a bevel gear 364' which drives the mechanism 365 including a switch for making connection between lines 615 and 616. 5 At all times when the motor is running, this switch is opened, while as soon as the motor stops the switch closes to connect line 615 to the line 616.

The other end of the armature shaft carries 10 an automatic brake 362 for stopping the motor whenever the supply of current thereto is cut off. This brake is actuated by a brake solenoid 362' which, when energized, releases the brake so that the motor may run, a spring or equivalent device applying the brake when the solenoid is de-energized. A circuit including a wire 617 and a wire 618 supplies current to the brake solenoid whenever the switch 607 is closed, the wire 617 being connected to the current carrying line 609, and the wire 618 being connected to the current carrying line 610. Obviously, therefore, the brake solenoid is connected across one phase of the alternating current supply, but is energized only when current is supplied to the 25 motor E.

Current for actuating the main switch solenoid 606 is supplied by a circuit including a wire 611 leading from the power line 603 to the switch 605, a line 612 leading from the switch 605 to 30 the main switch solenoid 606, and a circuit which will be further described, and which returns by way of wire 614 connected to the power line 602.

Current flowing through line 611, switch 605, line 612 and the main switch solenoid 606 flows 35 also through a line 620 leading to one terminal of a stop switch 621. The stop switch is biased to closed position, so that it normally bridges or connects its two terminals. Current, therefore, flowing through line 620 flows also through line 40 622, but will be interrupted if the switch 621 is opened. The line 622 is connected to one terminal of a second stop switch 623 having a construction similar to that of the stop switch 621. A further portion of the circuit, starting with 45 the line 611, continuing through the main switch solenoid 606, and through the stop switches just described, consists of a line 624 leading to one terminal of a third stop switch 625 similar to the stop switches 621 and 623. This portion of the 50 circuit therefore is always in condition to supply current to the main switch solenoid 606, unless one of the stop switches is depressed to interrupt the circuit. Inasmuch as the three stop switches 621, 623 and 625 are all in series, it will 55 be apparent that any one of the switches is effective for opening the circuit to the main switch solenoid.

Three start switches 628, 629 and 630 are provided, any one of which may be closed for closing 60 the circuit to the main switch solenoid 606 after it has been interrupted. These three switches, which are all connected in parallel, are all normally in open position. One of these switches 630 is adapted to close the connection between 65 the line 624 and the line 614. In such case, the circuit across the main power line 602 and line 603 is completed through the line 614, switch 630, switch 625, line 624, switch 623, line 622, switch 621, line 620, main switch solenoid 606, 70 line 612, switch 605 and line 611.

Similarly, the start switch 629 may be closed, if the operator is standing at such position that this switch is more accessible. In that case a circuit is closed across lines 602 and 603, through 75

line 614, switch 629, switch 623, wire 622 etc., through the main switch solenoid. In the same manner, closing of the start switch 628 completes a circuit across lines 602 and 603, through wire 5 614, switch 628, switch 621, wire 620, etc., through the main switch solenoid.

A spring or equivalent device (not shown) is arranged to open the main switch 607 whenever the main switch solenoid 606 is de-energized. 10 The closing of any one of the start switches energizes the main switch solenoid for effecting closing of the main switch, as described. In order to make it unnecessary to hold the starting switch closed, once the main switch solenoid has been 15 energized, an extra bar is provided for the main switch for short circuiting the starting switches in the following manner. A circuit is completed through line 614, line 631, a bar of the main switch 607, a line 632, a safety switch 633, a 20 line 634, a safety switch 635, a line 636, stop switch 625, line 624, stop switch 623, line 622, stop switch 621, line 620, main switch solenoid 606, line 612, switch 605 and line 611 connected to the power line 603. Current, with the parts in 25 this position, may flow through the main switch solenoid even though the start button be released. Since, however, the main switch 607 immediately opens if current ceases to flow through the main switch solenoid, the various switches just 30 mentioned, including switches 605, 621, 623, 625, 635 and 633 all control the motor. If any one of these is opened, the main switch solenoid is de-energized and the motor is stopped. The circuit, normally closed during operation of the 35 motor E, is indicated in Figure 47 by heavier lines than the other circuits.

It will be noted, therefore, that the motor may be stopped by an operator standing at any one of three stations arranged about the forming 40 machine. While I have herein illustrated three such stations with their switch equipment, it will be understood that any desired number of control stations may be provided. It will furthermore be noted that the machine may be 45 stopped due to an overload effecting opening of the switch 605. The safety switches 633 and 635, briefly referred to and hereinafter described in detail, also break the motor circuit in case of their actuation.

50 The line 616, above mentioned, connects the line 614 to the automatic switch in the mechanism 365. When this automatic switch closes, a circuit is completed through the wire 615, wire 640, wire 641, a contactor solenoid 642, line 643, 55 line 644 and line 645 connected to the main power line 603. This completes the circuit across the lines 602 and 603, and energizes the contactor solenoid 642 to close a switch 646. The closing of this switch completes a circuit through 60 line 647 connected to the main power line 602, switch 646, line 648, a trip solenoid 650, line 651, line 644 and line 645. A circuit is therefore completed across lines 602 and 603 to energize such trip solenoid 650.

65 As is shown in Figure 45, the trip solenoid 650 is connected by a link 653 to a lever arm 654 keyed at 655 to the shaft 71. To this shaft is also keyed a bevel gear 657 meshing with a similar gear 658 keyed to the vertical shaft 445. 70 It will be obvious, therefore, that when the trip solenoid 650 is energized, the shaft 445 will be rotated in the opposite direction to that effected by the worm wheel 444, this rotation swinging the lever 451 in a clockwise direction, as viewed 75 in Figure 32, to bring the left hand fork 453 into

engagement with the clutch shifting member 386 for swinging it in a clockwise direction and disengage the cone clutch 384 from its shoe 380. At the same time, the pin 383 is moved into engagement with one of the slots 382 in the clutch shoe. Since the automatic switch 365 is opened while the motor is running and closed when the motor stops, the trip solenoid 650 is energized each time the motor stops and de-energized when the motor starts. Due to this construction, each 10 time the motor stops, the cone clutch is automatically moved into its slow speed driving position so that when the motor is again energized the parts must start moving at a previously determined slow speed condition. 15

In convenient relationship to each of the three starting switches, is provided a switch for controlling movement of the main clutch 405 and connecting or disconnecting the gear 407 to or from the table driving mechanism. This clutch 20 is controlled by a clutch solenoid 660 (Figure 46), included in a circuit which may be connected across the lines 602 and 603 by a switch 661. This circuit includes wire 645, a wire 662, the clutch solenoid 660, wire 663, the switch 661, 25 wire 664 and wire 647. The switch 661 is controlled by a contactor solenoid which may be energized by the closing of any one of three switches 666, 667 or 668, which are the three switches located in convenient relation to the 30 starting switches. Upon closing of any one of these three switches, a circuit is completed across the main power lines 602 and 603. This circuit will include wire 645, wire 644, wire 669, contactor solenoid 665, a wire 670, any one of the 35 switches 666, 667, or 668, wire 671, wire 615, the automatic switch in mechanism 365, wire 616 and wire 614.

It will be noted that upon starting of the motor, the connection between wires 616 and 615 is 40 broken. The closing of any of the switches 666, 667 or 668 will therefore have no effect upon the clutch solenoid 660 if the motor is running, due to the break between the lines 615 and 616. This precaution is taken to prevent any possibility of 45 shifting of the main clutch during operation of the motor E.

The clutch solenoid 660 (Figure 46) is connected by a link 673 to an arm 674 of a lever freely rotatably mounted on a shaft 676 in turn rotatably mounted in a support 676' (Figure 30). A ratchet wheel 677 is keyed to the shaft 676. As the arm 674 is swung downwardly, a spring pressed pawl 678 carried by the arm engages a tooth of the ratchet wheel 677 and effects a partial rotation thereof. A dash-pot 680 is connected by a link 681 to the solenoid link 673. A spring 682 is connected to the opposite arm 683 of the lever from the arm 674. This is a coil spring tending to pull the arm 683 downwardly 50 when the clutch solenoid is de-energized. A lug 684 projects downwardly from the lever arm 683 and is engaged by an adjustable abutment screw 685 for limiting the downward movement of the 55 lever arm.

To the shaft 676 (see Figures 30 and 43) is secured a star wheel 687. Beneath the star wheel is the outer end of a clutch shifting lever 688 secured to shaft 689 of a main clutch shifting member 690. A roller 691 is carried by the outer end 70 of the lever arm 688 in position to be engaged by the teeth of the star wheel 687. A compression spring 692 disposed below an abutment 693 on the lower side of the lever arm 688 tends to swing the lever arm upwardly to maintain the roller 75

691 in engagement with the teeth of the star wheel, rotation of the star wheel therefore being effective for moving the lever through the medium of the roller 691 against the action of the 5 spring 692.

As illustrated in Figure 44 of the drawings, there is provided a spring pressed pawl 686 adapted to cooperate with depressions 686' in one side of the start wheel 687, to maintain the star wheel in the 10 position to which it is moved by the ratchet wheel 677 with the roller 691 in engagement with one of the high points of the star wheel. No latch mechanism is required to maintain the lever arm 688 in its raised position because at this time the 15 roller 691 is intermediate two of the points of the star wheel and is held upwardly in this position by the spring 692.

With a six-pointed star wheel as illustrated in the drawings, the clutch solenoid 660 will be effective for moving the star wheel one-twelfth of a revolution upon each actuation thereof.

The outer end of the lever 688 carries a set screw 695 which, as it nears its lowermost position as shown in Figure 43, engages a button 696 of a 25 switch 697 controlling a signal light circuit illustrated in Figure 48.

To protect the wires running to the various stations, suitable conduits are conveniently provided. For this purpose, a conduit 700 may be 30 used for carrying both the electric light wires and the wires of the control circuits leading to the contactor solenoids 642 and 665 from a main control box 701. The lead wires 601, 602 and 603 connected to the main power lines of the plant 35 may be led into the box 701 through a conduit 702. A conduit 704 carries the control circuits which, as illustrated in Figure 48, lead to the different control boxes about the machine. A conduit 705 is provided for the electric light circuit so that 40 when the button 696 is depressed by the screw 695, three lights are turned on, one adjacent each of the control stations. Thus, a signal light 706 is shown adjacent the start switch 628 and clutch control switch 666; a signal light 707 is provided 45 adjacent the start switch 629 and the clutch control switch 667, and a third signal light 708 is provided adjacent the start switch 630 and the clutch control switch 668. All three of these signal lights are lighted whenever the button 696 is 50 depressed by the screw 695.

From the foregoing it is obvious that whenever the star wheel 687 is moved into position to depress the clutch lever 688 and move the clutch to "out" position, the signal lights at all three operating positions are turned on. Due to the electrical connections thus provided, the signal lights may be illuminated under either of two conditions. One of these conditions is that which obtains at such time as the main motor E is operating 55 to drive the feeder mechanism but not the forming mechanism. The other condition obtains when the motor E is idle and the main clutch is in out position. The signal lights thus always indicate to the operator that the main clutch is 60 in "out" position. If the lights are lighted he is advised that it is safe to start the motor E to drive the feeding mechanism. He is also advised that if he is to drive the entire mechanism, including both the feeding mechanism and the 65 forming machine, he must press any one of the clutch solenoid switches before starting his motor. It is clear, therefore, that no matter where the operator may stand, he is informed as to 70 whether the clutch is in or out, and is thereby guided in his operation of the machine.

It is well known to those skilled in the art that from various causes the continuous flow of glass and the continuous feeding of gobs has, under certain circumstances, material advantages over the feeding of the gobs continuously 5 and then stopping for a period and starting up again. The exigencies of production of pressed glassware may on the other hand necessitate stopping of the forming mechanism for short periods. For instance, the glass may stick in 10 one of the molds, a part of the forming member may become over-heated, or some other unforeseen circumstance may necessitate the stopping of the forming machine. If it were necessary to always stop the feeding mechanism while 15 repairs or the like are being undertaken, the stopping of the flow of glass through the feeder might have various objectionable results. The driving mechanism just described is provided with a main clutch 405; and accordingly the 20 forming machine may be disconnected and the feeding mechanism then driven while the forming machine is stationary to permit work to be done in connection with the same. Each time that the motor is stopped, the cone clutch 384 25 is thrown out by downward movement of the trip solenoid 650 due to flow of current through the same, this current being supplied automatically by the mechanism 365 whenever the motor stops. At the same time that the cone clutch 30 384 is thrown out, the arm 69 (see Figure 2) is swung in a clockwise direction, thereby swinging the tunnel end of the chute 58 out from beneath the shearing mechanism 60.

One of the switches 666, 667 or 668 may be 35 closed to disconnect the main clutch 405, it being noted that at this time the motor is stopped and the wires 615 and 616 are connected through the switch in the mechanism 365. The motor may now be started to drive the feeding mechanism; 40 and since the chute 58 is no longer arranged to receive and transfer the gobs, the same fall into the waste chute 80 and are delivered to a point from which they may be returned to the glass 45 furnace. It is apparent, therefore, that my improved mechanism, including the driving means above described, permits the feeding mechanism to be operated so as to maintain the glass discharged therefrom in suitable condition during 50 temporary halting of the operation of the forming machine. The independent operation of the two mechanisms thus made possible is obviously of advantage. As soon as the forming machine has been brought up to speed again and the 55 various mechanisms are operating suitably for the production of pressed ware, the operator may, by hand, return the chute 58 to operative position.

Inasmuch as the main clutch 405 only has 60 one tooth, this clutch can only be thrown into engagement in a predetermined position. The gear ratio between the table driving gear 407 and the ring gear 408 is such that when the clutch does come into engagement, which is the position 65 in which they are illustrated in Figure 5, for example, the table and feeding mechanism are in predetermined relationship. Thus temporarily stopping the operation of the table while maintaining feeder operation does not destroy 70 the relationship which had previously been accurately ascertained between these two mechanisms, inasmuch as the throwing of the clutch 405 into operative position automatically resumes the relationship initially determined. 75

Safety switches

Mechanism has been above disclosed which makes it possible for the operator, no matter on which side of the machine he is standing, to stop the motor E. There is a plurality of molds on the forming machine, however, which make it difficult for the operator to keep close track of all of the operations of all of the forming mechanisms. The speed of the machine may 5 also make it difficult to stop the motor in time should some part of the mechanism operate in an abnormal manner. Safety switches are provided for promptly stopping the motor should 10 some dangerous positioning of parts of the mechanism necessitate stopping of the motor.

In Figures 38, 39 and 40 a switch is shown which opens if the press-head fails to rise in normal fashion. To the base 50 is secured a 15 supporting standard carrying a plate 713 secured to a hinge 714 pivoted at 715. A spring 712 is connected to the hinge 714 for resiliently holding the plate 713 in the position shown in Figure 20 39. A set screw 716 extends through the hinge 714 in position to engage the button of the press-head safety switch 635 (see Figure 47) carried by the standard 710. An L-shaped trip member 25 717 is secured to the plate 713 with one of its arms 718 extending horizontally and laterally from the standard 710. This standard is so positioned that the press head will engage the plate 30 713 if fluid pressure has not been admitted beneath the piston, or if such fluid pressure has failed to elevate the piston. Even though the 35 press head may have been suitably elevated, the screw peg may be lower than safety permits; and accordingly the arm 718 is arranged in such position that it is engaged by a peg in such abnormal position and swung on its hinge so as to actuate the safety switch 635. This, as clearly 40 brought out in the description of the automatic control, stops the motor E.

The cam mechanism which controls the position of the bottom plug 240, as referred to in connection with the take out mechanism, includes 45 the pivoted cam members 255 and 261. It may happen that the glass in the mold prevents outward movement of the plug, in which case the cam member 255 swings about its pivot 256 compressing the spring 257. In this case there is no 50 danger from a sticking plug 240.

It may happen, however, that after the plug 240 has been extended by operation of the cam member 255, broken glass or some other obstruction 55 may prevent return movement of the bottom plug 240 or permit only a partial return of the same. In such case the pivoted cam member 261 swings out of the way, the spring 263 being elongated to permit the cam roller 243' carried by the segmental gear to pass. In this case 60 the bottom plug 240 is in such a position as to interfere with the closing of the mold sections, and since it extends radially from the machine, it may break some part. A bottom plug safety switch mechanism such as shown in Figures 41 65 and 42 is arranged in position to be engaged by the cam roller 243' should this occur.

A standard 720 secured at 721 to the base 50 of the forming machine rotatably carries a hinge member 722. A horizontal arm 724 is secured to 70 the hinge member 722, its outer end carrying a trip abutment 725. The switch 633 is supported at 727 on the standard 720. A set screw 728 extends through the arm 724 in position to engage the switch 633. A return spring 729 normally 75 maintains the arm 724 in the position shown in

Figure 42. It is clear that should the cam member 261 fail to operate normally, so that the bottom plug is not completely returned to retracted position, the bottom plug safety switch 633 is actuated to stop the motor.

Many of the advantages of apparatus constructed in accordance with my invention have been pointed out in the course of the above description. Certain improvements result from the cooperation of the various parts of apparatus so 10 constructed. It will be noted that through independent driving of the feeding mechanism and of the forming machine, improved operation of the former is made possible. The driving connections further insure that the forming machine, 15 even though temporarily disconnected from the driving mechanism, can only be connected for driving again so that the formation of gobs of glass for delivery into the molds of the forming machine shall take place in synchronism with 20 operation of the forming machine. The driving mechanism is moreover of such an improved character that the parts automatically assume such a relation as to insure driving at low speed when driving is resumed, the change to high 25 speed drive also taking place automatically.

In addition to the advantages resulting from such driving of the two mechanisms, there is provided an adjustment which may be controlled 30 during driving by the motor for properly synchronizing the operation of the forming machine and that of the feeding mechanism.

This possibility of adjustment during the operation is highly desirable inasmuch as it enables the feeder to be advanced or retarded, as to its 35 cycle of operations, relative to the forming machine, thereby making it possible for the operator to easily make any adjustment required for changes in the characteristics of the glass or of 40 the gather.

The timing of various mechanisms which together cooperate to form an article are, according to principles of my invention, so co-ordinated that each operation occurs in proper sequence and is given the proper duration. It is furthermore to be noted that the timing of certain of the operations which are so related as to make it advantageous to maintain the same time interval between the same be altered together, so that this same relation is maintained while changing the 50 place in the complete cycle of the forming machine at which this group of operations take place. In this way, adjustment of the timing is made possible without disarranging the relation between operations which should be performed as 55 a group.

Due to the continuous rotation of the mold table, the speed of production is increased while decreasing the power requirements for the operation of the forming machine.

The invention also provides what may be considered as a take-out unit which is adjustable relative to the forming machine itself, whereby the unit may be adjusted relative to the forming machine for advancing or delaying the taking out operation while maintaining a predetermined 60 relationship between the take-out mechanism and the forming machine mechanism.

The invention also embodies a novel system of fluid distribution whereby fluids of different pressures may conveniently be distributed to different fluid pressure motors or to points where such fluid or fluid pressure may serve a desirable function or operation.

All of the above advantages are obtained in a 75

machine of comparatively simple construction in which most of the parts are readily accessible for repair, inspection or adjustment. This is particularly true as to the mold equipment itself which, 5 mounted on sub-bases above the main base and below the intermediate frame of the machine, is readily removable for replacement as may be required.

It will be apparent to those skilled in the art 10 that many changes in the construction, location, and arrangement of the parts, and in the manner of controlling the same, may be effected without change or departure from the inventive concept herein disclosed.

15 I claim:

1. The combination with a mold having a support member for the article being manufactured, means for moving the mold continuously through an orbit, means for opening the mold, an actuator 20 for moving the support member to move the article out of the mold, and a yieldable cam for cooperating with the actuator to move the support member, of a take out device comprising a recessed member and means for oscillating said 25 member between article receiving position and article discharging position, said member when in article receiving position being disposed in the path of an article supported on the support member of said mold so as to receive such article in 30 passing, said member being substantially without movement along said orbit when receiving the moving article.

2. In combination, a mold having a member 35 for moving the article being manufactured out of the mold after being molded, a movable mold carrier, driving means for the mold carrier, a projecting actuator for said member, yieldable cams for cooperating with the projecting actuator to move said member, and means engageable by said 40 projecting actuator for stopping the mold carrier driving means upon failure of the yieldable cams to shift said projecting actuator.

3. A take out mechanism including an article 45 engaging and holding member, means for oscillating said member arcuately about a horizontal axis to deliver articles being handled, an ejector reciprocable in a direction parallel to said horizontal axis for ejecting articles from said member, and timing means for synchronizing the reciprocations of said ejector with the oscillations of said 50 engaging and holding member.

4. The combination with a glass forming machine, of actuating means therefor comprising an electric motor, an electric start and stop device 55 for said motor, and a control circuit connected to said device comprising a plurality of manually operable switches arranged at various positions about the forming machine for controlling said device, and a safety switch operable automatically 60 by an element of the forming machine in abnormal position for controlling said device.

5. The combination with a glass forming machine, of actuating means therefor comprising an electric motor, an electric start and stop device 65 for said motor, a control circuit connected to said device having a plurality of switches for controlling said device, said switches being arranged at various positions about the forming machine, a clutch for connecting said actuating 70 means to the forming machine, and signals adjacent the various positions of said switches for indicating the engagement or disengagement of the clutch.

6. The combination with a glass forming machine, of actuating means therefor, operative 75

driving connections between said actuating means and said forming machine including a clutch controlling driving of said forming machine by said actuating means, and means for shifting said clutch, said shifting means being operable only 5 while said actuating means is at rest.

7. The combination with a glass forming machine, of actuating means therefor, operative driving connections between said actuating means and said forming machine including a clutch, a solenoid for actuating said clutch, and means for supplying current to said solenoid, said current supplying means being automatically cut off from the source of current supply during movement of said actuating means. 15

8. The combination with a glass forming machine, of a driving motor therefor, operative driving connections between said motor and forming machine including a clutch, a solenoid for shifting said clutch, and a circuit for supplying current to said solenoid, said circuit comprising a manually operable switch and a switch automatically opened upon starting of the motor. 20

9. The combination with a glass forming machine, of actuating means therefor, operative 25 driving connections between said actuating means and said forming machine including a clutch, power operated means for shifting said clutch, means for supplying power medium to said clutch shifting means to operate the same, and means 30 responsive to starting and stopping of said actuating means for automatically shutting off the supply of power medium to said clutch shifting means during movement of said actuating means.

10. In a glass forming machine, a mold, a rotatable forming member cooperating therewith, means for moving the forming member into engagement with the material in the mold, means for checking return movement of the moving means at an intermediate point, and screw out 40 mechanism for rotating the forming member while the moving means is at said intermediate point and automatic means operating subsequent to said rotation of the forming member for rendering said checking means ineffective thereby 45 permitting further return movement of said moving means.

11. In a glass forming machine, a mold, a movable frame, a rotatable forming plunger carried by the frame with limited vertical movement relative thereto, means for moving the frame toward the mold, said frame having an abutment for positively moving the forming member into engagement with the material in the mold, a check for arresting return movement of said frame at an 55 intermediate point, and screw-out mechanism for rotating the forming plunger to withdraw the same from an article formed in the mold, and means for automatically operating said check to arrest said frame until the forming plunger is 60 withdrawn and for thereafter rendering said check ineffective thereby permitting further return movement of said frame.

12. In a glass forming machine, a mold, a hollow rotatable forming plunger, means for moving 65 the plunger relative to the mold to form an article, means for passing cooling fluid into said plunger, and means for spraying a coating against the outside of said plunger prior to a forming operation.

13. In a glass forming machine, a rotatable mold carrier, a mold carried thereby, and a take out unit including means for coordinating the operation of the take out unit with the movements of the mold carrier, said take out unit be- 75

- ing bodily circumferentially adjustable relative to the axis of rotation of the mold carrier.
14. In a glass forming machine, a movable mold carrier, a mold carried thereby, a take out unit 5 bodily adjustable in unchanging relation to the path of travel of the mold, and common driving means for the mold carrier and the take out unit.
15. In a glass forming machine, a rotatable mold carrier, a mold carried thereby, a take out 10 unit, and driving means rotatable with the mold carrier for actuating the take out unit, said take out unit being bodily circumferentially adjustable relative to the axis of rotation of the mold carrier.
16. In a glass forming machine, a movable mold carrier, a mold carried thereby, mold opening mechanism, and a take out unit including means 15 for coordinating the operation of the take out unit with the movements of the mold carrier and timing means carried by the take out unit for timing the operation of the mold opening mechanism, said take out unit being bodily adjustable in unchanging relation to the path of travel of the mold.
17. In a glass forming machine, a rotatable mold carrier, a mold carried thereby, mold opening mechanism, a take out unit, driving means 20 rotatable with the mold carrier for actuating the take out unit, and a control device carried by the take out unit for timing the opening operation of the mold, said take out unit being bodily circumferentially adjustable relative to the axis of rotation of the mold carrier.
18. In a glass forming machine, a mold, press 25 mechanism movable toward and from the mold, said press mechanism comprising a rotatable forming member for cooperating with the mold to shape an article therein, means for moving the press mechanism toward and from the mold, screw out mechanism for rotating the forming member, means for timing the movement of the press mechanism toward the mold, means for timing the screw out, means for timing the movement of the press mechanism away from the mold, and means for simultaneously varying the 30 timing of the screw out operation and of the movement of the press mechanism away from the mold without varying the timing of the movement of the press mechanism toward the mold.
19. In a glass forming machine, a rotatable mold table, a mold carried thereby, press mechanism comprising a rotatable forming member for 35 cooperating with the mold to shape an article therein, and a cylinder and piston for actuating the press mechanism, a valve for controlling flow of pressure fluid relative to the cylinder, screw out mechanism for rotating the forming member, timing means for the valve, separate timing means for the screw out mechanism, each timing means comprising cooperating elements, one of each being carried by the table, the other element of each timing means being carried by a normally stationary support, and means for separately adjusting each of said supports angularly 40 about the axis of rotation of the table.
20. In a glass forming machine, a mold, press mechanism cooperating with the mold comprising a cylinder and piston, a valve for controlling flow of pressure fluid relative to the cylinder, control devices for the valve, and means for adjusting the timing of a plurality of said control devices simultaneously.
21. In a glass forming machine, a rotatable 45 mold table, a mold carried thereby, press mechanism cooperating with the mold comprising a cylinder and piston, a valve for controlling flow of pressure fluid relative to the cylinder, control devices for the valve, and means for angularly adjusting a plurality of said cams simultaneously about the axis of rotation of the table.
22. In a glass forming machine, a rotatable mold table, a mold carried thereby, press mechanism 50 cooperating with the mold comprising a cylinder and piston, a valve for controlling flow of pressure fluid relative to the cylinder, control devices for the valve comprising cams and normally stationary means for supporting the cams, and means for angularly adjusting a plurality of said cams individually or collectively about the axis of rotation of the mold table.
23. In a glass forming machine, a mold, press mechanism cooperating with the mold comprising a cylinder and piston, a valve for controlling flow of pressure fluid relative to the cylinder, control devices for the valve, and means for adjusting the timing of a plurality of said control devices individually or collectively.
24. In a glass forming machine, a mold, a rotatable forming member cooperating with the mold, means for reciprocating the forming member, screw out mechanism cooperating with said rotatable forming member, timing means for timing the operation of said reciprocating means and timing means for timing the operation of said screw-out mechanism, each of said timing means comprising an orbitally movable contact element and a normally stationary cam engageable thereby, said cams being connected together and shiftable as a unit to simultaneously adjust the timing of both the operation of said reciprocating means and the operation of said screw-out mechanism.
25. In a glass forming machine, a mold, a rotatable forming member cooperating with the mold, means for reciprocating the forming member, screw out mechanism cooperating with said rotatable forming member, timing means for timing the operation of said reciprocating means, timing means for timing the operation of said screw-out mechanism, said timing means comprising orbitally movable contact elements and normally stationary cams engageable thereby, a pair of shiftable supports, each support carrying certain of said cams, and means for shifting said supports individually or collectively.
26. A take-out mechanism including a frame 55 oscillatable from article receiving position to article discharging position, a bifurcated member on said frame for receiving an article while said member is stationary at said first mentioned position, and a reciprocable ejector cooperating with said bifurcated member at said second mentioned position for discharging the article.
27. The combination with a glass forming machine comprising a movable support, a mold carried thereby, a plunger carried by said support 60 for forming an article in said mold, and means for raising and lowering said plunger during movement of the support, of actuating means for the forming machine comprising an electric motor, an electric device for stopping the motor, and a safety contact element extending beneath the path of travel of said plunger for tripping said stopping device, said element being closely adjacent the lowermost point of said plunger as the latter passes over in normal position so as to 65 70 75

trip said device if the plunger should be in abnormally low position.

28. The combination with a glass forming machine comprising a movable support, a mold carried thereby, a rotatable mandrel carried by said support for forming an article in said mold, means for raising and lowering said mandrel during movement of the support, and screw-out mechanism for rotating the mandrel, of actuating means for the forming machine comprising an electric motor, an electric device for stopping the motor, and a safety contact element extending beneath the path of travel of said mandrel for tripping said stopping device, said element being closely adjacent the lowermost point of said mandrel as the latter passes over in normal position so as to trip said device if the mandrel should be in abnormally low position.

29. In a glass forming machine, a mold, a movable frame, a forming plunger carried by the frame with limited vertical movement relative thereto, a spring-pressed follower carried by the frame, a cylinder and piston for moving the frame to pressing position to form an article in said mold and for moving the frame to retracted position, a check for arresting return movement of said piston within the limit of said available relative movement, and control means for said check for causing preliminary arresting of the piston and for causing subsequent release of the piston for further return movement.

30. In a glass forming machine, a mold, a movable frame, a rotatable forming mandrel carried by the frame with limited vertical movement relative thereto, a cylinder and piston for moving the frame to pressing position to form an article in said mold, a check for arresting return movement of said piston within the limit of said available relative movement, screw-out mechanism for rotating the forming member and timing means for initiating such return movement of the piston prior to the operation of the screw-out mechanism and releasing the check subsequent thereto to permit further return movement of the piston.

31. A take-out mechanism comprising a frame pivotally mounted on a horizontal axis, a recessed article receiving member carried by said frame, and means for swinging said frame from article receiving position to article discharging position and back again, said member when in article receiving position being disposed in the path of the article to be handled with the recess opening reversely to the direction of travel of the article so as to receive said article in passing, said member being substantially without movement along said path when receiving the article.

32. A take-out mechanism comprising a frame pivotally mounted for oscillatory movement about a horizontal axis from receiving position to discharge position and back again, a member carried by said frame having a recess for receiving an article to be transferred, the recess in said member opening in a direction parallel to the horizontal axis of the frame, and discharge means cooperating with said member and operative at said discharge position to discharge an article therefrom.

33. The combination with a mold and a carrier for moving the mold in an orbit of a take-out mechanism comprising a frame pivotally mounted adjacent the orbit of the mold on a horizontal axis generally parallel to a tangent to the adjacent portion of said orbit, a recessed article receiving member carried by said pivoted

frame, the recess in said member opening in a direction parallel to said tangent and reversely relative to the direction of travel of the article, and means for swinging said frame about said horizontal axis.

34. The combination with a glass forming machine, of actuating means therefor, operative driving connections between said actuating means and said forming machine including a clutch controlling driving of said forming machine by said actuating means, electrical mechanism for shifting said clutch, and a circuit closable only while said actuating means is at rest for supplying current to said electrical mechanism for actuating the same to shift the clutch.

35. The combination with a glass forming machine, of actuating means therefor, operative driving connections between said actuating means and said forming machine including a clutch controlling driving of said forming machine by said actuating means, and mechanism for shifting said clutch into and out of operative position, said shifting mechanism being operable only while said actuating means is at rest for shifting said clutch in either direction.

36. The combination with a glass forming machine, of actuating means therefor, operative driving connections between said actuating means and said forming machine including a clutch controlling driving of said forming machine by said actuating means, and mechanism for shifting said clutch, said shifting mechanism being operable only while said actuating means is at rest for obtaining any actuation of said shifting mechanism.

37. The combination with a forming machine comprising a mold, a movable mold carrier for carrying said mold through an orbit, and apparatus cooperating therewith for the performance of a cycle of operations including the freeing of a molded article from surrounding mold parts, of a take-out device at a take-out station adjacent the orbit of the mold, said device comprising a recessed member, and means for moving said member to receive an article by obstructing the further movement of the article by the forming machine and away from said orbit after receiving the article, said member being substantially without movement along said orbit when receiving the moving article and the recess in said member opening in a direction to receive the molded article during movement of the article as the machine moves orbitally.

38. In a glass forming machine, a mold, press mechanism movable toward and away from the mold, said press mechanism comprising a rotatable forming plunger shaped to form threads in plastic material in the mold having additional threads of the same pitch as the threads formed on the article's engaging portion of the plunger, and a vertically reciprocable element for forcing the plunger into the plastic material, means providing threads for cooperating with said additional threads on the plunger for screwing the plunger out of the molded article, said threaded means and said plunger being carried in common by and having limited vertical movement relative to said element, means for rotating the plunger to effect a screwout operation, and means for causing retraction of the vertically reciprocable element within the limit of said available relative movement and for causing operation of the screw-out mechanism subsequent to such retraction.

39. In a glass forming machine, a mold, press mechanism cooperating with the mold and comprising a rotatable forming plunger shaped to form threads in plastic material in the mold and a reciprocable element for forcing the plunger into the plastic material, said plunger being carried by and having limited movement relative to said element, means for checking retraction of said element at an intermediate point permitted by such limited movement without moving said plunger, means providing threads of the same pitch as the threads formed in the plastic material for withdrawing the plunger and including screw-out mechanism intermittently actuated for rotating the plunger, said plunger having a threaded portion cooperating with the threads of said withdrawing means, and timing means for causing retraction of said element prior to actuation of the screw-out mechanism.
- 20 40. In a forming machine, a mold, press mechanism cooperating with the mold and comprising a rotatable forming plunger shaped to form threads in plastic material in the mold and a vertically reciprocable element for forcing the plunger into the plastic material, said plunger being carried by and having limited vertical movement relative to said element, checking means for temporarily arresting lifting movement of said element at an intermediate point, means providing threads of the same pitch as the threads formed in the plastic material for withdrawing the plunger and including screw-out mechanism for rotating the plunger, said plunger having a threaded portion cooperating with the threads of said withdrawing means, and timing means for initiating such lifting movement of said element prior to the operation of the screw-out mechanism and releasing the checking means subsequent thereto to permit further lifting movement of said element.
- 40 41. The combination with molding apparatus comprising a series of orbitally movable molds each having a support for the article being molded, means for orbitally moving the molds, means for opening the molds, and means for operating the article supports to free the articles from surrounding mold parts in said orbit, of a take-out device positioned at a point adjacent the orbit of the molds comprising a recessed member, means for moving said member into position to obstruct the orbital movement of an article on its support so that the orbital movement of the support causes the article to enter the recess in said obstructing member and to lodge there, and means for moving said member to transfer the article away from said orbit.
42. In combination, a rotatable mold table, a mold thereon, means for continuously rotating the table, and a take-out mechanism cooperating therewith comprising a recessed member, the recess in said member being adapted to receive the article during orbital movement of the latter, and means driven in synchronism with the mold table for swinging said member about a horizontal axis to and from article receiving relation to the mold orbit to transfer articles from the mold, said member being substantially without movement along said orbit when receiving the moving article.
43. In a glass forming machine, a mold, a frame, a forming member carried by the frame with limited vertical movement relative thereto, a cylinder and piston for reciprocating the frame and forcing the forming member into the material in the mold, means for positively checking return movement of the piston due to fluid pressure beneath the same at a point not beyond the travel

permitted by said vertical movement between the forming member and frame, means for disengaging the forming member from the molded article, and automatic means for subsequently rendering said checking means ineffective thereby permitting further return movement of said piston.

44. In a glass forming machine, a rotatable support, a plurality of molds carried thereby, forming plungers moved arcuately about the axis of the support with the molds, one cooperating with each mold, means for moving the plungers relatively to the molds to form articles therein, and means moved arcuately about the axis of the support with the plungers for spraying a coating against the outside of the plungers prior to a forming operation.

45. In a glass forming machine, a rotatable support, a plurality of molds carried thereby through an orbit, threaded rotatable forming plungers moved along said orbit with the molds, one cooperating with each mold, means for moving the plungers relative to the molds to form articles therein, and means moved along said orbit with the plungers for spraying a coating against the outside of the plungers prior to a forming operation.

46. In a glass forming machine, a rotatable support, a plurality of molds carried thereby, hollow threaded rotatable forming plungers carried by said support, one cooperating with each mold, means for moving the plungers relative to the molds to form articles therein, means for passing cooling fluid into said hollow plungers, and means carried by said support for spraying a coating against the outside of the plungers prior to a forming operation.

47. In a glass forming machine, a mold, a threaded rotatable mandrel cooperating therewith to form an internally screw-threaded article and having additional threads of the same pitch as the threads formed on the article engaging portion of the mandrel, pressing means for causing said mandrel to enter plastic material in the mold to shape the same, means providing threads for cooperating with said additional threads on the mandrel for screwing the latter out of the molded article, said mandrel and said threaded means being together so connected to said pressing means by a lost motion connection as to have limited vertical movement relative thereto, means for rotating the mandrel to effect a screw-out operation, and means for causing an initial lifting movement of the pressing means relative to said threaded means and said mandrel prior to the screw-out operation to an extent permitted by said lost motion connection.

48. In a forming machine, a rotatable carrier, a plurality of molds supported thereon, a plurality of press mechanisms on said carrier one for each mold, each press mechanism including a rotatable forming plunger and a longitudinally reciprocable element for forcing the plunger into plastic material in the mold, a driven gear rotatable about the axis of the carrier, means for rotating said gear, and screw-out mechanisms on the carrier one cooperating with each rotatable forming plunger, each screw-out mechanism including a drive shaft parallel to and offset from the axis of the respective plunger, gearing operatively connecting said drive shaft in driving relation with said plunger, a gear orbitally movable with the carrier and meshing with said driven gear, and means comprising a clutch for intermittently connecting said orbitally movable

gear with the offset shaft for rotating the plunger to free the same from the molded article in the mold.

49. In a forming machine, a rotatable carrier, a plurality of molds supported thereon, a plurality of press mechanisms on said carrier one for each mold, each press mechanism including a rotatable forming plunger and a longitudinally reciprocable element for forcing the plunger into plastic material in the mold, a driven gear rotatable about the axis of the carrier, means for rotating said gear, and screw-out mechanisms on the carrier one cooperating with each rotatable forming plunger, each screw-out mechanism including a drive shaft parallel to and offset from the axis of the respective plunger, gearing operatively connecting said drive shaft in driving relation with said plunger, a gear orbitally movable with the carrier and meshing with said driven gear, and means for intermittently connecting said orbitally movable gear with the offset shaft for rotating the plunger to free the same from the molded article in the mold, said connecting means comprising a clutch, a cam and a shifting device for the clutch controlled by the cam, rotation of the carrier effecting movement of the device relative to the cam to effect shifting of the clutch.
50. The combination with molding apparatus comprising a series of orbitally movable molds each having a support for the article being molded, means for orbitally moving the molds, means for opening the molds, and means for moving the article supports to move the articles

from the mold at a station in said orbit, of a take-out device comprising a recessed member, and means actuated in synchronism with the orbital movement of the molds for moving said recessed member to and from article receiving relation to the orbit of the molds to permit an article to enter and lodge within the recess during orbital movement of the molds and article supports and to transfer the article away from the mold, said member being substantially without movement along said orbit when receiving the moving article.

51. In a forming machine, a mold, press mechanism including a rotatable forming plunger and a longitudinally reciprocable element for forcing the plunger into plastic material in the mold, a pinion carried by said plunger for rotating the same, and screw-out mechanism including an element reciprocable with the reciprocable element and provided with gear teeth for rotating said pinion.

52. In a forming machine, a mold, press mechanism including a rotatable forming plunger and a longitudinally reciprocable element for forcing the plunger into plastic material in the mold, a pinion fixed to said plunger, and screw-out mechanism including an element reciprocable with the reciprocable element and provided with gear teeth continuously meshing with said pinion for rotating the same, and means for intermittently actuating said element.
